UNITED STATES PATENT OFFICE.

THADDEUS CAHILL, OF WASHINGTON, DISTRICT OF COLUMBIA, ASSIGNOR
TO JAMES B. LAMBIE, E. HILTON JACKSON, GEORGE FREDERICK CAHILL,
AND ARTHUR T. CAHILL, TRUSTEES.

TYPE-WRITING MACHINE, LINOTYPE-MACHINE, TYPE-SETTING MACHINE, OR OTHER KEYBOARD PRINTING INSTRUMENTALITY.

SPECIFICATION forming part of Letters Patent No. 657,478, dated September 4, 1900.

Application filed June 30, 1898. Serial No. 684,880. (No model.)

To all whom it may concern:

Be it known that I, THADDEUS CAHILL, a citizen of the United States, residing at Washington, in the District of Columbia, have invented certain new and useful Improvements in Type-Writing Machines, Linotype-Machines, Type-Setting Machines, or other Keyboard Printing Instrumentalities, of which the following is a specification.

10 Certain features of my invention are designed for use in type-writing machines, linotype-machines, type-setting machines, and other keyboard printing instrumentalities in which letters are produced (printed or selected) by operating upon keys, while other features of my invention are peculiar to type-writing machines. I shall first describe my invention as applied to a type-writing machine and will then point out how certain important features of my invention may be applied to linotype-machines, type-setting machines, and other keyboard printing instrumentalities.

As applied to a type-writing machine the objects of my invention are to make a type-writing machine in which the operator can depress a plurality of keys in succession to make successive letters without having to release the key first depressed before depressing the next key. In type-writing machines as ordinarily constructed it is necessary, it should be understood, to release one key before another key can be depressed to make another letter. This necessitates an abrupt or staccato touch on the part of the operator in which each movement is made by itself.

35 In playing a pianoforte, on the other hand, or an organ with the usual legato touch there is none of this abruptness. One movement overlaps another. The finger which has just 40 depressed a key is rising while another finger is depressing another key to produce the next note. By reason of this overlapping of the movements—this fact that several movements in different phases are taking place at the same time—performers can play scales and produce other effects on a pianoforte, as is well known, with the most remarkable rapidity. The touch in which one movement overlaps another, in which one key begins to

descend before the preceding key has been 50 released, is commonly termed by musicians (for reasons which I need not go into here) the "legato touch." A principal object of my present invention is to enable the operator to use a legato or overlapping touch in 55 depressing the keys of a type-writer—that is to say, to depress a key before he has released or while he is releasing the last key depressed—and to obtain proper printing. By doing this I make the operating easier and 60 more natural and at the same time materially increase the speed, for in type-writing machines as ordinarily constructed the limit of rapidity of action is the time in which the operator can both depress and release the 65 key, while by my invention the limit of rapidity of action is the time in which the operator can depress the key. He does not need to release it before he depresses another.

70 The features of my invention above referred to by which the operator is enabled to depress a key without waiting to release the key or keys previously depressed may be applied to type-setting and linotype-machines as well as to type-writing machines. 75 The remaining features of my invention are specially applicable to type-writing machines; and it consists in certain features of construction hereinafter described by which a type-writing machine of simple and durable construction is made adapted to write letters one at a time and having a few keys acting singly and in different combinations to control a much larger number of characters.

80 I shall first describe a novel form of type-writing machine (illustrated in Figures 1 to 14 of the accompanying drawings) in which my invention is embodied. After that I shall illustrate certain features of my invention as applied to certain other forms of type-writing 85 machines. Then I shall illustrate the application of my invention to a linotype-machine, and, finally, I shall point out and specifically claim the parts, improvements, and combinations in which the invention consists.

90 95 In the accompanying drawings, Fig. 1 is a longitudinal vertical section, partly in elevation, the upper portion of the machine being

broken away, illustrating a type-writing machine constructed to embody my invention. Fig. 2 is a sectional view, also partly in elevation, in a plane at a right angle to the plane 5 of the preceding figure, and in this view various portions of the mechanism are omitted. Fig. 3 is a detail view similar to Fig. 1, illustrating more clearly and on a larger scale a portion of the mechanism shown in Fig. 1. Fig. 4 is a view similar to Fig. 3 but with the electromagnet in section and certain portions of the mechanism of Fig. 3 broken away, showing the arrangement of the circuit. Fig. 5 is a view, partly in plan and partly in section, 15 on the line 5 5, Fig. 1, illustrating certain portions of the mechanism. Fig. 6 is a similar view on the line 6 6, Fig. 1. Fig. 7 is a detail view, partly in plan and partly in section, illustrating the arrangement of the radial levers, the pin-carrier, and the group-controlling levers, whereby the pins in the pin-carrier and the radial levers are controlled, and in this figure a portion of each of the group-controlling levers is broken away. Fig. 8 is 20 a detail view showing the arrangement of the group-controlling levers with the push-pieces connected to them and by which they are connected with the oscillating motor-frame. Fig. 9 is a plan view illustrating the 25 center ring and the means by which the radial levers are fulcrumed, a portion of the cap-ring (screwed to the top of the center ring, milled to match the milled slots in the center ring, and coacting with the center 30 ring to retain the radial levers in place) being broken away. Fig. 10 is a sectional view, partly in elevation, on the line 10 10, Fig. 9. Fig. 11 is a plan view of the oscillating pin-carrier by which the group-controlling levers 35 are connected, each as required, with the different radial levers that they serve to actuate. Fig. 12 is a detail view, a front elevation of said pin-carrier. Fig. 13 is a detail perspective view of the stop 182, hereinafter described; and Fig. 14 is a detail, a rear elevation, illustrating the spacing mechanism. Fig. 15 illustrates certain features of my invention as applied to a somewhat different form of type-writing machine, and Fig. 16 40 illustrates the same features of invention as applied to a linotype-machine.

The machine illustrated in Figs. 1 to 14, inclusive, resembles in many ways the machine illustrated in a pending application of mine, Serial No. 668,737, filed February 1, 1898; but the machine illustrated in Figs. 1 to 14 of the present application differs from the machine illustrated in the pending application before-mentioned, (a) in that it is constructed to 45 write letters one at a time only, while the machine illustrated in the application of February 1, 1898, aforesaid is adapted to write letters in pairs, (b) in that it is constructed to enable the operator to depress a key to 50 make a letter without having first to release the key or keys depressed to make the preceding letter, and (c) in various other par-

ticulars, the most important of which are pointed out in the statement of claim at the end hereof.

The machine shown in Figs. 1 to 14 of the accompanying drawings in illustration of my invention consists, essentially, of (a) a set of type-bars suitably mounted and striking to a common printing-center; (b) a set of radial levers corresponding to the type-bars aforesaid and each connected with the type-bar to which it corresponds; (c) an electromagnet and an oscillating frame impelled thereby and serving to impel all the type-bars aforesaid, each type-bar as required; (d) keys fewer in number than the type-bars and means controlled by said keys acting singly and in different combinations, whereby the type-bars aforesaid are connected, each as required, with the motor device aforesaid and said motor device brought into action to impel the type-bar thus connected with it; (e) means connected with and actuated by the motor device aforesaid, whereby said motor device as 90 the type-bar approaches the printing-point cuts off the power from itself and releases the various parts controlled by the key, so that the type-bar with the other parts controlled by the key, including the motor device itself, 95 can resume their normal positions, whereby the operator is enabled to depress another key to make another letter without having to wait to release the key first depressed, and (f) a paper-carriage, spacing mechanism, ribbon mechanism, and other usual devices, which being old and well known I need not describe.

The main frame.—The main frame of the machine figured in the drawings consists, essentially, of (a) a bed-plate 1, (b) a top plate 2, (c) a center ring 40, (d) standards 41 41, bolted to the bed-plate and serving to support the center ring 40, the group-controlling levers, the bell-crank levers, the motor-frame, the circuit-closing frame, the pin-carrier-driving frame, the normal frame, and various other parts hereinafter described, and (e) four columns 42 42 42 42, which rise from the center ring 40 to support the top plate 2.

The type-bars and the means for controlling them.—50 50 are the type-bars, mounted by means of hangers 51 51 in the usual fashion. A few type-bars only are shown in the drawings, but any convenient number may of course be used. The machine figured in the drawings has thirty-nine.

52 52 are the radial levers, which are set in the milled slots 53 53 in the center ring 40 and are fulcrumed by means of a circular or segmental wire 54 and held in place by means of the cap-ring 55, which is milled to correspond with the milling of the center ring 40 and is attached thereto by suitable screws. Each of the radial levers 52 corresponds to one of the type-bars 50 and is connected with the short arm of such type-bar by means of a link 56.

Underneath the inner ends of the radial

levers 52 52 are the pins 60 60, (one pin to every four radial levers as the machine illustrated in the drawings is constructed,) mounted in the oscillating pin-carrier 61 and held 5 in their normal positions (shown in Figs 1, 2, and 12) by light expansive springs 62 62, which bear upon collars 63 63, attached to the pins 60 60, forcing said collars down on the lower disk of the pin-carrier. Each of the 10 pins 60 60 serves to give movement to the different radial levers of the group controlled by it, each as required, the pin-carrier 61 being oscillated to bring the pins into operative relation with the different radial levers controlled by them, each as required. 15

Just below the pins 60 60 are the group-controlling levers 65 65, which are centered on rods 66 66, supported in the standards 41 41, said standards being milled to produce slots 20 to receive the several group-controlling levers aforesaid. The proximate ends of the group-controlling levers 65 65 are made segmental, as illustrated in Figs. 5 and 8, so that however the pin-carrier 61 may be vibrated 25 each of the pins 60 60 always lies over the corresponding group-controlling lever 65. Tilting pieces 67 67 are hinged to the group-controlling levers 65 65. An oscillating frame 70 underlies said tilting pieces. Said oscillating frame is mounted by means of the arm 71 of the rock-shaft 72 and a bridle-lever 73, to both of which it is pin-jointed. To the other arm 74 of the rock-shaft 72 the armature 75 is connected. Said armature 75 and the core 76 (which is attached to a plate 77, that is bolted to the bottom of the bed-plate 1) lie within a non-ferruginous tube 78, around which the energizing-coil 79 is wound. The magnet thus formed serves to give movement 30 to the oscillating frame 70 aforesaid, and thereby to whatever one of the group-controlling levers 65 65 may have its tilting piece 67 67 overlying said frame. A tilting piece 67^a, hinged to one of the group-controlling levers 65, normally overlies the motor-frame 70, while all the other tilting pieces 67 67 lie out of the path of movement of said oscillating motor-frame. 45

We have seen that each of the group-controlling levers 65 65, with the corresponding pin 60, control a different group of the radial levers 52 and type-bars 50. The question then of what type-bar shall be impelled when the oscillating frame 70 strikes up depends 50 upon (a) what one of the group-controlling levers 65 has its tilting piece in the path of movement of the motor-frame 70, and (b) what position the vibratory pin-carrier occupies, whether its normal position or some one 55 of the positions into which it is moved respectively by the depressing of the keys B', B², and B³. To control the nine tilting pieces 67 67, there are nine keys C C, each of which serves, as we shall soon see, when depressed 60 to swing the tilting piece 67 connected with the group-controlling lever 65 that corresponds to such key over the oscillating frame 65

70 to receive movement therefrom, and the three keys B', B², and B³ serve to vibrate the oscillating pin-carrier 61 into the different 70 positions required to connect each of the group-controlling levers 65 65 aforesaid with the different radial levers 52 52 of the group to which it corresponds.

The keyboard. — Let us now consider the arrangement of the keys and the parts which they actuate. 75

The keys B', B², and B³, controlling the pin-carrier 61, are designed to be operated ordinarily and properly by the thumb, while the 80 nine keys C C, corresponding to and controlling the different group-controlling levers 65 65, are designed to be regularly and properly operated by the fingers. The space-key G is designed to be operated by the ring-finger. 85

Overlying the keys B', B², and B³, C C C, and the space-key G is a set of key-corresponding and key-actuated levers (which, for greater convenience and to distinguish them from the key-levers, I shall sometimes hereinafter term "key-actuated" levers or "key-corresponding" levers) b' b² b³, c c c, and g. These levers are fulcrumed in front by means of a rod 80, which is set in the bar 81. Said bar is milled to receive the key-actuated levers aforesaid. It serves as a stop to limit the upward movement of the keys, and it is attached by screws 82 82 to lugs 83 83, that rise from the bed-plate 1. 90

To the rear end of each of the key-actuated levers b' b² b³ c c c, and g is hinged a releaser-arm 84, which is held by a contractile spring 85 normally in contact with the lug 86 on the metal end piece 87, attached to the rear end of the corresponding key-lever. (See Figs. 1, 3, and 4.) The releaser-arms 84 84 aforesaid serve each to connect the key-actuated lever to which it is attached with the corresponding key-lever (B', B², or B³, C C C, or G,) so that when said key-lever is depressed in front by the operator it rises back of the fulcrum and lifts the corresponding key-actuated lever through the releaser-arm 84; but about the instant the type-bar strikes to print—say, preferably, when the type-bar has 100 moved about one-fourth to one-third or even less of the distance from its normal position to the printing-center—the releasing-frame 90, which is centered at 91 and connected by the link 92 with the arm 93 of the magnet-actuated rock-shaft, strikes the releaser-arm 105 84, moving it off of the end piece 87, connected with the key-lever, and allowing all the parts to return instantly to their normal positions and before the operator has released 110 the key-lever. 115

Bell-cranks 95 95, fulcrumed by means of the rods 96 96 (set in milled slots in the standards 41 41) and having their horizontal arms overlying the key-actuated levers c c c (each 120 of which is furnished with a projection c', rising above it to act upon the corresponding bell-crank 95) and having their vertical arms connected by links 97 97 with the tilting 125

pieces 67 67, serve to connect the key-actuated levers *c c c* with the tilting pieces 67 67, pivoted to the corresponding group-controlling levers 65 65, so that each of the keys CCC 5 when depressed lifts, through the releaser-arm 84, the corresponding key-actuated lever *c*, which serves (a) to swing, through its bell-crank 95 and link 97, the tilting piece 67 connected with the corresponding group-controlling lever 65 over the oscillating motor-frame 70 to receive movement therefrom; (b) to lift the normal frame 140, centered at 141 and which acts on one of the bell-cranks 95 aforesaid and through such bell-crank 10 15 and the link 97 connected therewith swings the normal tilting piece 67 off from over the motor-frame 70, and (c) to lift the circuit-closing frame 150, centered at 151 and having an arm 152, carrying the battery-connected spring 153, pressing said battery-connected spring over against the contact-screw 154, (to which one end of the magnet-coil 79 is connected, the other end of said coil being connected with the battery, as shown in Fig. 4,) 20 25 thereby closing the circuit of the magnet before described, so that the core 76 attracts the armature 75, which thereupon lifts the motor-frame 70, thereby giving movement to whatever one of the tilting pieces 67 overlies it and 30 to the group-controlling lever 65 to which said tilting piece is connected and to the pin 60 overlying said group-controlling lever. Said pin in turn gives movement to whatever one of the radial levers 52 52 it underlies, and 35 the radial lever thus moved gives movement through the link 56 to the corresponding type-bar 50, throwing the type up against the printing-point. As the type-bar approaches the printing-point the releasing-frame 90 40 (centered, as before said, at 91 and connected by the link 92 with the arm 93 of the magnet-actuated rock-shaft 72) strikes the releaser-arm 84, moving it off of the end piece 87, attached to the corresponding key-lever. Thereupon 45 the key-actuated lever returns to its normal position, releasing the various parts controlled by it and, among others, releasing the circuit-closing frame 150, which, returning to its normal position, breaks the circuit of the motor-magnet aforesaid, whereupon 50 the armature 75, with the oscillating frame 70, return to their normal positions under the influence of the contractile spring 160, releasing the tilting piece 67, group-controlling lever 65, pin 60, radial lever 52, and type-bar 50, all of which immediately return to their normal positions, being assisted thereto by suitable springs, some of which are omitted from the drawings. The return of 55 all the parts to their normal positions takes place in a very small fraction of a second, and the operator can now depress another key to print another letter without having first to release the key before depressed. 60 65 Each of the key-levers C C C (which from the fact that they are designed to be normally and regularly operated by the fingers of

the hand as distinguished from the thumb we may properly term "finger-keys" or "finger-key levers") serves when depressed to cause some one of the type-bars of the group corresponding to it to be actuated by the oscillating motor-frame 70, and if no one of the keys B', B², and B³ (which from the fact that they are designed to be normally and regularly depressed by the thumb we may term "thumb-keys" or "thumb-key levers") is at the same time depressed that one of the type-bars of the group is actuated whose radial lever 52 overlies the corresponding pin 60, when the pin-carrier 61 is in its normal position, with the stop 180 attached to it, held in contact with the lug 184 of the stop 182 by the contractile spring 183. The keys B', B², and B³ serve to oscillate the pin-carrier 61 and thereby to control what one of the type-bars of a group shall be actuated. For this purpose a pin-carrier-driving frame is used, consisting of (a) rock-shaft 170; (b) three driving-arms 171, 172, and 173, upon which the keys B', B², and B³, respectively, act through the arms 84 84 84, levers *b*, *b*², and *b*³, and pivoted push-pieces 174 174; (c) a connecting-arm 175, connected by the link 176 with the pin-carrier 61, and (d) a stop-arm 177, carrying adjustment-screws 178 178, (adjustable by means of lock-nuts,) which strike the stops 179 179, Figs. 5 and 6, attached to the rear end of the key-actuated levers *b* *b*². The pins 60 60, it will be observed, are arranged equidistant from each other in the pin-carrier 61, and each of them controls a group of four of the radial levers 52 52 and type-bars 50 50. Each pin, as before said, in all its different positions overlies the corresponding group-controlling levers 65. Each pin normally underlies the first radial lever 52 of the group of radial levers controlled by it, and it is oscillated to underlie the second, third, and fourth radial levers of its group, respectively, by depressing the keys B', B², and B³, respectively. Thus if the key B' be depressed said key gives movement through the releaser-arm 84 to the corresponding key-actuated lever *b*', which lifts the stop 179, carried by it, up into the path of movement of the corresponding adjustment-screw 178, carried by the stop-arm 177, and at the same time said key-actuated lever *b*' acts, through the push-piece 174, pivoted to it, upon the arm 171 of the rock-shaft 170, moving said rock-shaft in the direction of the arrow, Fig. 1, and through the arm 175 and link 176 moves the pin-carrier 61 in the direction of the arrow, Figs. 7 and 11, so bringing each of the pins 60 60 into operative relation with the second radial lever (counting in the direction of the arrow, Fig. 7) of the group of radial levers 52 52, controlled by it, in which position all the parts are arrested by one of the adjustment-screws 178, 120 carried by the stop-arm 177, coming in contact with the stop 179, carried by the key-actuated lever *b*'. If the key B² be depressed, the corresponding key-actuated lever *b*², act- 125 130

ing in like manner through its push-piece 174 upon the arm 172 of the rock-shaft 170, moves the pin-carrier 61 until each of the pins 60 60 underlies the third radial lever of the group 5 controlled by it, in which position all the parts are arrested by one of the adjustment-screws 178, carried by the stop-arm 177, coming in contact with the stop 179, carried by the key-actuated lever b^2 . If the key-lever B^3 be 10 depressed, the key-actuated lever b^3 corresponding to and controlled by it acts through its pivoted push-piece 174 upon the arm 173 of the rock-shaft 170 and through said rock-shaft and its arm 175 and the link 176 moves 15 the pin-carrier 61 in the direction of the arrow, Fig. 7, until the pins 60 60 each underlies the fourth one of the radial levers 52 52 of the group controlled by it, in which position all the parts are arrested by the stop 180, 20 which is attached to the pin-carrier 61, coming in contact with the lug 181 of the stop 182, which stop is screwed fast to the lower surface of the center ring 40. When the connection between the thumb-key lever B' , B^2 , 25 or B^3 is depressed and the corresponding key-actuated lever b' , b^2 , or b^3 is broken by the action of the motor-impelled releasing-frame 90 upon the releasing-arm 84, the pin-carrier 61 and the parts connected therewith are 30 turned by the contractile spring 183 to their normal positions, with the stop 180, carried by the pin-carrier 61, resting against the lug 184 of the stop 182. The pin-carrier 61 is mounted upon an axle 185, set in the cap-ring 55, 35 on which axle it is held by the collar 186 and a set-screw. (Not shown in the drawings.)

To prevent the motor-magnet from acting to give movement to the oscillating frame 70 while the pin-carrier 61 is taking position, 40 there is a frame 190, Figs. 1 and 4, centered at 191 and lying underneath the keys B' , B^2 , and B^3 , so that it is depressed by said keys when acted on by the operator. The frame 190, Fig. 4, is connected through the space-magnet H^{51} with one pole of the battery, and 45 it makes connection when in its normal position with the spring 192, which is connected with the coil 79 of the motor-magnet. When any of the keys B' , B^2 , or B^3 is depressed, the frame 190 impelled thereby moves away from the spring 192, breaking connection therewith; but as the key impelling said frame approaches the limit of its movement said frame 50 comes in contact and makes connection with the spring 193, likewise connected with the coil 79. The frame 190 then, with the springs 192 and 193, serves, it will be seen, (a) to establish connection between the battery and the coil 79 of the motor-magnet when the keys 55 B' , B^2 , and B^3 are all of them in their normal positions, (b) to break this connection so soon as any one of said keys begins to be depressed and to keep it broken while said key is being depressed and the carrier 61 positioned, 60 and (c) to reestablish the connection as soon as the key B' , B^2 , or B^3 depressed reaches the limit of its movement and the pin-carrier

comes to rest. By this construction the oscillating frame 70 is prevented from striking to impel a type-bar while the pin-carrier 61 70 is moving into position.

The shift-key, Figs. 1 and 5, is marked 195. It is attached by a stem 199 to the frame 196, which is fulcrumed at 197 and connected at 198 by a pull-down wire (not shown in the drawings) with one of the bell-cranks carrying the shift-rod (not shown in the drawings) at the top of the machine, by which the platen is shifted, and which being old and well known in the art and forming no part of my invention I need not describe here.

The carriage, the ribbon mechanism, the interlinear-spacing mechanism, the alarm-bell, and other usual details may be of any suitable kind, and as many forms of such devices are well known in the art and as they constitute no part of my invention I have not thought it best to illustrate them in the drawings or to burden this specification with any description of them.

Any suitable form of spacing mechanism whatever may be used. I prefer, however, to use a spacing mechanism such in principle as those illustrated in a number of prior patents to me, such as the patent of August 8, 1893, No. 502,700, and that of March 1, 1898, No. 600,119, consisting, essentially, of (a) a rack c^{37} , Fig. 14, suitably connected with the paper-carriage, which latter is urged in the direction of the arrow, Fig. 14, by the usual carriage-motor-spring device (not shown in the drawings) or by any other suitable means; (b) the fast dog H^3 and the loose dog H^4 ; (c) the dog-carrying lever H , by which said dogs are vibrated into alternate engagement with the rack c^{37} aforesaid; (d) a normal stop H^{34} , serving, ordinarily, to limit the movement which the loose dog H^4 executes under the influence of its contractile spring H^{36} when withdrawn from the rack c^{37} to a single tooth-space of said rack; (e) a space-enlarging lever H^{62} , to which said normal stop H^{34} is attached, and whereby said normal stop is lifted when the space-key G is depressed from its normal position, thereby permitting the loose dog H^4 when freed from the rack c^{37} an increased movement until it is arrested by the stop H^{38} , attached to the bridle-lever H^5 , and (f) means for actuating the dog-carrying lever H .

The key-actuated lever g , upon which the space-key G acts through the releaser-arm 84, is connected with the space-enlarging lever H^{62} by a push-up H^{63} , so that whenever the space-key G is depressed it acts through the releaser-arm 84, lever g , push-up H^{63} , and space-enlarging lever H^{62} to lift the stop H^{34} , thereby to permit an increased movement of the dog H^4 , space-rack c^{37} , and paper-carriage connected therewith.

H^{41} H^{41} are hangers, and H^{42} H^{42} are stops, Fig. 14, and H^{37} is the returning-spring for the dog-carrying lever H .

To give movement to the lever H and the

dogs connected thereto, I may use either (a) a space-magnet H^{51} , which may be either in series with the motor-magnet, as shown diagrammatically in Fig. 9, or in parallel with it and connected through the lever H^{52} or otherwise to actuate the dog-carrying lever H , or (b) I might connect the key-actuating levers to actuate the dog-carrying lever H through the circuit-closing frame 150 (to 10 which an arm might be attached, connected by a link with the lever H) or in any other suitable manner, or, (c,) which is better than the last, I may connect the motor-magnet by its armature 75 to actuate said dog-carrying lever H in any convenient manner—as, for example, by connecting the lower part of the motor-frame 70 to the front end of a lever of the first class, whose rear end is connected by a pull-down with the dog-carrying lever 20 H . Any one of these constructions may be followed and any other suitable construction may of course be used instead.

Instead of operating the releasing-frame 90 by the same electromagnet which actuates the type-bars it may, if desired, particularly in those machines in which a large number of magnets are employed to operate the type-bars—as, for example, in the devices described in the Letters Patent to me, Nos. 30 600,119 and 600,120, dated March 1, 1898—be operated by means of an electromagnet other than that acting to impel the type-bars, the electromagnet serving to actuate the releasing-frame 90 being in such case controlled 35 by the keys in any suitable manner—as, for example, by the circuit-closing-frame 150—in which case the circuit of the magnet actuating the releasing-frame may obviously be (a) entirely independent of the circuit of the type-bar-impelling electromagnet, or (b) in parallel with it, or (c) the electromagnet actuating the releasing-frame 90 may be placed in series with the type-bar-impelling electromagnet.

45 I prefer to actuate the releasing-frame 90 or its equivalent by a motor, and the combination of such frame with a motor for actuating it and with other elements of the mechanism constitute important features of 50 my invention, but in any paragraph of claim at the end hereof in which a releaser or a releasing-frame is made an element and in which no reference is made to a motor actuating said releaser or releasing-frame I do 55 not in such claim limit myself to actuating said releaser or releasing-frame by a motor, for, in fact, while it is very advantageous to actuate it by a motor it is not absolutely indispensable that it be so actuated.

60 Fig. 15 shows my invention as applied to the form of type-writing machine illustrated in Figs. 1 to 7 of the drawings of the before-mentioned Letters Patent No. 604,001, dated May 10, 1898. 1 is the bed-plate; 2, the top 65 plate; 3, columns rising from the bed-plate to support the top plate, and 4, one of the side bars attached to the columns 33. A plurality

of rails, as 7 8 13 14 15, &c., (seen in cross-section in Fig. 15,) serve to support the various parts and require no explanation here, being fully described in the Letters Patent aforesaid. 50 50 are the type-bars. m , m' , m^2 , and m^3 are different parts of the carriage mechanism, as hereinbefore explained. c^6 is a lever answering to one of the keys (the key 75 C^6) of the machine described in the Letters Patent aforesaid. E^{10} is the motor-magnet, E^{11} its armature, and E^{12} the motor-frame connected to said armature and like it centered at E^{15} . E^{18} is the core of the motor-magnet. 80 c^6 is one of the group-controlling levers which serve to lift the rear ends of the different groups of the type-bar-connected levers f (all as fully described in the specification of the Letters Patent aforesaid, No. 604,001) when 85 connected with the motor-magnet by the corresponding key-actuated lever c^6 , lifting, through the push-piece 32, the tilting piece E^6 up into the path of movement of the motor-frame E^{12} , whose circuit is at the same 90 time closed by the key lifting the circuit-closing frame 18 overlying it. The arrangement of the circuits being fully described in the Letters Patent aforesaid, No. 600,001, need not be described here further than to say that whenever any key is depressed the main or working circuit is closed through the motor-magnet E^{10} and also through some one of the magnets D D' D^2 D^3 (according to what key is depressed) controlling the fulcrum-frames d , d' , 100 d^2 , and d^3 . The construction, arrangement, and operation of all the other parts shown in Fig. 15 and not herein fully described are fully described in the Letters Patent aforesaid, No. 604,001. At the same time a parallel circuit is closed, as fully described in the pending application aforesaid, through the releasing-magnet B^{22} . The arrangement of the circuit is or may be that fully described in the pending application aforesaid with reference to Fig. 1 or Fig. 1^a thereof. So much 110 for that portion of the structure illustrated in Fig. 15, which is old in this application, being fully described in the Letters Patent aforesaid, No. 604,001. C^6 C^6 are the key-levers, 115 to each of which the releaser-arm 84 is pivoted in front at 111, said releaser-arm having a projection 84^a formed thereon to be struck in due time when the key is depressed by the releasing-frame 90, centered at 91. To 120 the releasing-frame 90 is attached an arm B^{18} , carrying an armature 100, which lies in the field of the electromagnet B^{22} . A contractile spring 85^a holds the releasing-frame in its normal position with the platinum contact-point carried by its arm B^{18} resting against and making connection with a similar contact-point in the adjustment-screw B^{17} . The electrical connections of the contact-screw B^{17} , the arm B^{18} , and the electromagnet B^{22} 130 are the same as those of the similarly-marked parts in the drawings of the Letters Patent aforesaid, No. 604,001, which being fully described in the specification of said Letters

Patent need not be further described here. To the motor-frame E¹² is attached an extension 120, to which is connected a push-piece 121, held in place by guides 122 122. Said 5 push-piece serves, as the type-bar impelled by the motor-magnet E¹⁰ approaches its printing-point, to strike the releasing-frame 90, moving the arm B¹⁸ away from the contact-screw B¹⁷, thereby rupturing the circuit of the motor-magnet E¹⁰ and permitting the type-bar to return instantly to its normal position. Immediately after thus breaking the circuit of the motor-magnet E¹⁰ the releasing-frame 90, acting on the releasing-arm 84, releases 10 the key-corresponding lever c, the normal frame C, and the circuit-closing frame 18 (both of which are fully described in the Letters Patent aforesaid) controlled thereby, thereby permitting all the parts to return to 15 their normal positions.

In the device of Fig. 15 it will be observed the circuit is broken first when the push-piece 121 strikes the releasing-frame 90 by the arm B¹⁸ of said frame moving away from the contact-screw B¹⁷, with which it is normally in connection, before the key-actuated lever c, being released by the knocking out of the releaser-arm 84 by the frame 90, allows the circuit-closing frame 18 to return to its normal position, and, further, if for any reason—as, for example, when the operator strikes two keys at once, so that the type-bars are locked on each other and unable to reach the printing-point, thereby blocking the motor-frame E¹² and push-piece 121 and preventing them from executing their normal movements—the releasing-frame 90 is not moved in due time by the motor-magnet E¹⁰, the magnet B²², which is adjusted in any of the ways 25 known to electricians—such, for example, as those referred to in the Letters Patent aforesaid, No. 604,001—to be somewhat slower acting than the motor-magnet E¹⁰, attracting the armature 100, attached to the arm B¹⁸ 30 of the releasing-frame 90, gives movement to said arm and frame, producing the effects above described—that is, breaking the circuit of the electromagnets and releasing the key-corresponding lever c—whereby all the parts 35 50 are left free to return to their normal positions whether the key C⁶ depressed be released or not and whereby the operator is left free to put down a second key before he has released the first.

Fig. 16, which is a view in general similar to the preceding figure, shows my invention as applied to a linotype-machine of the kind invented by Ottmar Mergenthaler and now well known in the art and in general and 55 public use throughout the United States and which is described in divers well-known United States patents, and particularly in that to said Mergenthaler dated September 16, 1890, No. 436,532. The pull-downs h h, 60 connected with the character-corresponding levers f f of a permutational character-selecting device of the kind fully described in

the before-mentioned Letters Patent No. 604,001, dated May 10, 1898, are connected to operate the levers P P, (centered at p p 70 and held by the contractile springs h' h' normally against the felted stop-bars h² h²), and through said levers to operate the push-pieces Q Q, thereby to give movement to the escapement-lever R and pawls r' r², by which the fall of the matrices from the magazine-tube or channel-box is controlled. It is to be understood that in Fig. 16 only one of these magazine-tubes, with the escapement device corresponding thereto, is shown, there being, 80 however, as is well known to all persons skilled in the art, a similar magazine-tube and escapement device for each different kind of matrix—that is, for each different letter or other character. In Fig. 16 only so much of 85 the well-known linotype structure is shown as is necessary to illustrate the manner of applying my present improvement thereto, the assembling devices, whereby the matrices when released are carried to the assembling- 90 block and arranged into a line thereon, the devices whereby the space-wedges are inserted and the justification effected, the devices whereby the slug is cast, trimmed, and arranged in the galley, the distributing mechanism, and other necessary parts of the machine, which are already well known in the art and fully described in divers well-known United States patents to Mergenthaler, particularly that of September 16, 1890, No. 436,532, aforesaid, being omitted.

Instead of using electromagnetic motor mechanism to impel the type-bars pneumatic or other suitable motor mechanism may be used, as explained in the specifications of the 105 Letters Patent to me, No. 600,120, dated March 1, 1898, and No. 604,001, dated May 10, 1898. The motor-controlling mechanism of whatever kind, at least when a single motor device is used, whether the contact-points of 110 an electromagnet or the valve mechanism of a pneumatic motor or the other controlling mechanism of any other kind of motor, may be connected to be actuated by the frame 150, which is, in fact, the universal frame of the 115 present machine and the equivalent of the frame 18 in the Letters Patent aforesaid, No. 604,001. (See the specification of the said Letters Patent, in which it is pointed out that such a frame may be used to control other 120 motor mechanism than electromagnetic mechanism.)

Instead of using a single electromagnet or other motor device to impel all the type-bars obviously a different electromagnet or other 125 motor device might be used for each different group of type-bars, as in the construction fully set forth in the Letters Patent aforesaid, No. 600,120, or a different electromagnet might be used for each different type-bar—as, for 130 example, in the construction fully described in the Letters Patent to me, No. 600,119, dated March 1, 1898. The key-actuated levers c, c, c, b', b², b³, and g obviously correspond to the

keys of one set in the machines illustrated in the drawings of the Letters Patent aforesaid, No. 600,119 and No. 600,120, dated March 1, 1898, and No. 604,001, dated May 10, 1898, 5 and so far as certain important features of my invention are concerned it is wholly immaterial what the type-bar-controlling devices controlled by the key-actuated levers $c c' b b' b^2 b^3$ may be, whether they be (a) type-bar-controlling devices of the kind described in the Letters Patent aforesaid, No. 600,119, dated March 1, 1898, having a different motor-magnet for each different type-bar, or (b) type-bar-controlling devices of the kind described 10 in the Letters Patent aforesaid, No. 600,120, having a different motor for each different group of type-bars, or (c) type-bar-controlling devices of the kind described in the Letters Patent aforesaid, No. 604,001, and 15 illustrated in Fig. 15 of the accompanying drawings, or of the kind illustrated in Figs. 1 to 14 of the accompanying drawings, in which a single motor device is used to impel all the type-bars of the set, or (d) any other suitable 20 kind of type-bar-controlling mechanism whatever may be used, for, as the drawings in this case clearly show, when viewed in the light of the Letters Patent aforesaid and of my pending application before mentioned, 25 Serial No. 668,737, filed February 1, 1898, the essential features of my invention with relation to the automatic releasing of the type-bar-controlling devices, so that a key can be depressed to print without first releasing the 30 key before depressed, may be applied to any sort of type-writing machine, linotype-machine, type-setting machine, or other keyboard printing instrumentality by (a) employing a number of key-actuated levers, as $c c' c$, &c., answering to the keys of the instrument to which it is desired to apply my invention, 35 said key-actuated levers being applied either to operate the keys of such instrument or to operate the parts which said keys actuate, 40 and (b) employing keys at the keyboard equal in number to the number of the key-actuated levers aforesaid, said keys being arranged to control said key-actuated levers after the fashion illustrated in the accompanying drawings—say with a releaser-arm, as 45 84, connecting each key with the corresponding key-actuated lever and a releasing-frame, as 90, controlled, preferably, by a universal frame, as 150, actuated by the key-actuated levers aforesaid 50 and acting through a motor-magnet or any other suitable mechanism upon said frame 90 to disconnect the key-actuated lever corresponding to the key depressed from such key, thereby to permit the return of the key-actuated lever and the parts controlled thereby to their normal positions in advance of the 55 release of the key.

While making no statement of claim in this place and while referring the reader for a formal statement of claim to the paragraphs of 60 claim at the end hereof, it may be well to

point out briefly some of the most important features of my present invention.

(a) An important feature of my invention (and one which, so far as I am informed, is broadly new with me) consists in the use of a part set in motion in consequence of the depressing of the key and acting when the key has been depressed and is at rest in its depressed position to release the various parts operated by the key to permit them to return to their normal positions in advance of the release of the key. One important advantage of this feature of my invention is the mechanical simplicity which it gives to the device, as the drawings show. Another important advantage lies in the fact that the releasing is not effected until an instant of time after the key, whereby another key may be depressed to print while the key first depressed is still held down, has been depressed, thus leaving time for the motor mechanism called into action by the depressing of the key to operate. I am not aware that any part operating in this manner has ever been used in a type-writing machine. The part serving for this purpose in the structure illustrated in the drawings is the releasing-frame 90, impelled by the motor-magnet 79; but obviously some other part than the releasing-frame 90, impelled, if desired, in some other manner than by means of an electromagnet, may be used instead of said releasing-frame 90 and magnet 79 to effect the releasing.

(b) Another important feature of my invention (and one which, so far as I am informed, is broadly new with me) consists in combining motor mechanism (preferably motor mechanism which is normally stationary, but which acts when a key is depressed) for impelling the type-bars or other parts controlled by the keys with suitable releasing mechanism, whereby when a key has been depressed to print another key of the same set may be depressed to print before the key first depressed is released. By this means the touch is made to be very light indeed and the play of the keys is reduced, so that the operator is enabled to use all the fingers of the hand, even the weakest ones, readily upon the keys, and thus by using a finger movement to employ the legato or overlapping touch, which it is easy and natural to use when the touch is light, but which is more difficult and less advantageous when the touch is heavy, as it necessarily is in the machines in common use, in which the type-bars and other parts are impelled by the force applied by the operator to the keys; but as certain important features of my invention may be used without motor mechanism it will be understood that when I do not make motor mechanism or a motor device of some kind by some suitable form of words an element of any one of the combinations set forth in the paragraphs of claim at the end hereof I do not in such paragraph of claim limit myself

to using motor mechanism, but claim the thing set forth in such claim, whether motor mechanism be used or be not used.

(c) Another important feature of my invention (and one which, to the best of my information, is broadly new) consists in operating the releasing mechanism by power other than that exerted upon the key. Thus in the drawings the releasing-frame 90, which acts upon the releaser-arm 84, is operated by the magnet 79, Figs. 1 and 4; but obviously some other form of motor-operated releasing means might be used, and while I prefer to operate the releasing means by some form of motor device I do not, I wish it to be very distinctly understood, limit myself to the use of a motor device for releasing in any paragraph of claim in which a motor device or motor mechanism for releasing is not made by some suitable form of words an express element of the combination set forth in such claim.

(d) Another important feature of my invention (and one which, to the best of my information, is broadly new with me) consists in the use of a single releasing device (whether it be a frame, as 90, or some other device) common to a plurality of latches or other releasable connections and serving to free such connections each as required. In the drawings as already described the common releasing-frame 90 serves to act positively upon all the releaser-arms 84 each as required, thereby to release all the levers *c c' b' b² b³ g &c.*, each as required; but while I consider it advantageous to use the same releasing-frame or other common releasing device to act upon all the releaser-arms 84 or their equivalents each as required obviously within the broad principle of my invention a releasing device may be used to release a plurality of arms 84 or their equivalents without being used to release the whole set of said arms. In other words, two or more releasing-frames might be used each acting upon a plurality of releaser-arms 84 each as required.

(e) Another important feature of my invention consists in using a single releaser-arm, as 84, (or some equivalent part,) for a plurality of type-bars. The releaser-arm 84, it will be seen, controls mechanism which in turn actuates all the type-bars of a group, each type-bar as required, all which, so far as I am informed, is broadly new with me.

(f) Another important feature of my invention (and one which, so far as I am informed, is broadly new with me) consists in releasing a motor-controlling device to permit the same to return toward its normal position in advance of the release of the key. In Figs. 1 to 14 the form of motor-controlling device illustrated is the frame 150, controlling the circuit of the electromagnet 97; but it will be understood that some other suitable form of motor and of motor-controlling device may be used, if desired, and, further, it will be

understood that within the broad principle of my invention in this regard the motor-controlling device may be released by releasing means quite different from those illustrated in the drawings as well as by the releasing devices shown in the drawings.

(g) Another important but (as has been already seen) by no means indispensable feature of my invention consists in effecting the releasing by means of the same power device which impels the type-bar or other type-controlling device. One advantage of this is that the point in the travel of the type-bar or other type-controlling device at which the releasing is to be effected is readily controlled; but, as has been already clearly pointed out, a different motor device may be used to operate the releasing device from the motor device or motor devices used to operate the type-bars, matrix-freeing escapement devices, or other type-controlling devices, whatever these may be. It will be understood, therefore, that when in any of the paragraphs of claim at the end hereof I speak in any form of words of a motor device or of motor mechanism for releasing without clearly expressing in apt words that said motor device is the same motor device which impels a type-bar or the type-bars that I do not limit myself to the construction in which the motor that releases is also the type-bar-impelling motor.

(h) It has been proposed heretofore (see, for example, the patent to Flower, No. 426,931, dated April 29, 1890, and the reissue of the same, No. 11,391, dated November 28, 1893,) to connect the key-lever and the corresponding type-bar together in such manner that when the trip is effected said key-lever and type-bar resume their initial positions simultaneously; but in my preferred construction illustrated in the drawings there is no connection between the key-lever, as *B' B² B³ C C C*, or the key-actuated levers, as *b' b² b³ c c c*, and *g*, and the type-bars, whereby either the key-lever itself and the type-bar (or even the key-actuated lever and the type-bar) are caused to resume their initial positions simultaneously, and, in fact, the key-actuated lever, having a very much less distance to travel than the type-bar to return to its initial position, would naturally resume its initial position before the type-bar could resume its initial position, and there are reasons also why it is preferable (but not indispensable) that the key-actuated levers should resume their initial position without being delayed until the type-bars resume their initial positions, and, in fact, I have found it advantageous in my machines to adjust things in such manner that the releasing-frame 90 strikes the releaser-arm 84 and effects the release when the type-bar has moved, say, about one-third the distance (sometimes more and sometimes less) from its normal position to the printing-point, so that the key-actuated lever, as *c c' f' f² or f³*, sometimes actually resumes its initial position before

the type-bar has even commenced its return movement and long before it resumes its initial position. This increases the speed of the touch, and both the type-bar and the key-actuated lever, as $c\ c$ or $b' b^2 b^3$, in the device figured in the drawings should be and are constructed to resume their initial position while the key-lever is still held down, and, 10 finally,

(i) There are many other points of difference between my mechanism figured in the drawings and all prior devices of which I am aware heretofore proposed for releasing the 15 type-bars or paper-feeding devices of a type-writing machine. The essential points of novelty I shall endeavor to point out in the statement of claim at the end hereof, and I wish it to be very distinctly understood that 20 while there are many differences between the construction figured in the accompanying drawings and the prior attempts in the art, (none of which attempts, however, so far as I am aware, has ever resulted in the production 25 of a commercially-useful machine, if they have even resulted in the production of a working machine of any kind,) some of which differences have been hereinbefore pointed out, I do not limit myself to 30 structuring a machine having all these novel features, since each of several novel features of my invention may be used, with or without modification, whether the other novel features be used or not. I wish protection 35 for each of the novel features of my invention set forth in the accompanying claims, and it will be understood that many modifications may be made in the mechanism figured in the drawings and hereinbefore described by skilled mechanics without material departure from the spirit of my invention and without essential change in result. The releaser-arm 84 is one form of latch; but 40 some other form of latch may be used instead of it. A latch is one form of releasable connection between the key and the parts actuated by the key; but some other form of releasable connection may doubtless be used instead of a latch in certain of the combinations 45 hereinafter set forth in which the term "releasable connection" is used.

I use the word "mechanism" in the paragraphs of claim at the end hereof in a sense broad enough to include as well a plurality 50 of devices as a single device. Thus "motor mechanism" includes in its meaning a plurality of motor devices as well as a single motor device. By "releasing means" I mean means for releasing, by "tripping means" 55 means for tripping, and so on. By "motor mechanism," or by the narrower term "a motor device," I mean something which operates by power from a source external to the fingers of the operator. An electromagnet is 60 one form of motor device, but many other forms of motor device are known, some of which might be used instead of electromag-

nets in carrying out certain broad features of my invention. It will be understood, therefore, that when in any paragraph of claim at the end hereof I use the words "motor mechanism" or "motor device" I mean to include under those words other forms of motor mechanisms and of motor devices as well as electromagnets. Whenever I speak 75 of a plurality of things I mean more than one of those things. Thus when I speak in any of the paragraphs of claim at the end hereof of a plurality of type-bars I mean more than one type-bar, when I speak of a plurality of latches I mean more than one latch, when I speak of a plurality of keys I mean more keys than one, and so on; but I do not mean to limit myself to any particular number of parts by the term "plurality," nor under that term to limit myself to all the parts of a kind in a machine. I use the term "keyboard printing instrumentality" in this specification, and particularly in the statement of claim at the end hereof, in a broad and inclusive 90 sense as referring to any machine, mechanism, or device having a keyboard and used as instrumental or auxiliary to printing, and in particular I include under this term "keyboard printing instrumentality," (a) all 95 kinds of type-writing machines, whether of the type-bar or key-wheel variety, (b) type-setting machines, and type-composing devices, (c) linotype-machines and other line-casting machines, and (d) other machines, mechanisms, or devices in which the successive letters of a line are produced, printed, selected, registered, or recorded by or in consequence 100 of operating upon keys.

I do not claim herein anything that is 105 claimed in my other pending applications, Serial No. 522,435, filed September 8, 1894, and Serial No. 601,520, filed August 3, 1896; but it may be well to observe in this place that while many of the claims of the aforesaid application, Serial No. 522,435, filed September 8, 1894, are broad enough to cover 110 and are intended to cover the combinations which they set forth, whether used in one kind of keyboard instrument or another, each and every claim of this application is limited by 115 some feature of construction or some element of combination expressly set forth in it to a type-writing machine or other printing instrumentality. 120

What I do in this specification claim as new and of my own invention, and desire to secure by Letters Patent hereunder, is—

1. In a type-writing machine having a plurality of type-bars striking to a common printing-center, and keys for controlling said type-bars, the combination with a key of means constructed to permit said key, when depressed for the printing of a letter, to remain depressed after said letter has been printed 125 and while a subsequent letter is being printed without interfering with the due printing of such subsequent letter; said means including, (a) a type-bar-controlling member actu-

- ated by said key; and (b) a normally-stationary intermittently-vibratory element acting, when said key has been depressed and is at rest in its depressed position, to release the 5 type-bar-controlling member actuated by said key from said key, thereby to permit said type-bar-controlling member to return toward its normal position in advance of the release of said key.
- 10 2. In a type-writing machine having type-bars, and in combination, (a) a key; (b) a type-bar-controlling member, actuated by said key; (c) a connection intermediate said key and said type-bar-controlling member; and (d) a part set in motion in consequence of the depressing of the key aforesaid and acting, when said key has been depressed and is at rest in its depressed position, upon the connection aforesaid, to disconnect the type-bar-controlling member aforesaid from the key aforesaid, thereby to permit the return of said type-bar-controlling member toward its normal position in advance of the release of said key, all the parts being constructed, arranged and operating in such a manner that when the key aforesaid is depressed to print, another key can also be depressed to print, without waiting to release the key first depressed.
- 15 3. In a type-writing machine having a plurality of type-bars striking to a common printing-center, and in combination with said type-bars, type-bar-controlling mechanism, including, (a) a key; (b) a type-bar-controlling member, actuated by said key; (c) a latch for connecting the key and type-bar-controlling member aforesaid; (d) a spring for said latch; and (e) a vibratory releaser, normally stationary, but controlled by the key aforesaid, and acting, when said key is depressed, upon the latch aforesaid to disconnect the key aforesaid and the type-bar-controlling member aforesaid, actuated by said key, thereby to permit said type-bar-controlling member to return toward its normal position before the key controlling it is released, all the parts being constructed, arranged and operating in such a manner that when the key aforesaid is depressed to print, another 20 key can also be depressed to print, without waiting to release the key first depressed.
4. In a type-writing machine having a plurality of type-bars striking to a common printing-center, a type-bar-controlling mechanism, including, (a) a key; (b) a type-bar-controlling member actuated by said key; and (c) a motor, acting when the key aforesaid is depressed to release the type-bar-controlling member aforesaid, permitting it to return toward its normal position, without waiting for the key controlling it to be released, all the parts being constructed, arranged and operating in such a manner that when the key aforesaid is depressed to print, another 25 key can also be depressed to print, without waiting to release the key first depressed.
5. In a type-writing machine having type-bars, and in combination, (a) a key; (b) a type-bar-controlling member, actuated by said key; (c) a connection intermediate said key and the type-bar-controlling member aforesaid, wherethrough said key, when depressed, gives movement to said type-bar-controlling member; and (d) a normally-stationary intermittently-vibratory motor device, controlled by the key aforesaid and acting, when said key is depressed, upon the connection aforesaid to disconnect the type-bar-controlling member aforesaid from the key aforesaid, thereby to permit said type-bar-controlling member to return toward its normal position in advance of the release of the key. 70
6. In a type-writing machine having type-bars, and in combination, (a) a key; (b) a type-bar-controlling member, actuated by said key; (c) a connection intermediate said key and the type-bar-controlling element aforesaid, wherethrough said key, when depressed, gives movement to said type-bar-controlling element; (d) a releasing-frame; and (e) a motor impelling said releasing-frame, and acting through said releasing-frame upon the connection before mentioned as intermediate the key and type-bar-controlling member aforesaid to release the type-bar-controlling member aforesaid. 75
7. In a type-writing machine having type-bars, and in combination, (a) a key; (b) a type-bar-controlling member actuated by said key; and (c) an electromagnetic releasing device acting, when the key aforesaid is depressed, to release the type-bar-controlling member aforesaid, permitting it to return toward its normal position in advance of the release of the key; all the parts being constructed, arranged and operating in such a manner that when the key aforesaid is depressed to print, another key can also be depressed to print, without waiting to release the key first depressed. 80
8. A type-writing mechanism, including, in combination, (a) a key; (b) a normally-stationary motor device; (c) a motor-controlling device, actuated by the key aforesaid and serving, when said key is depressed, to bring the motor device aforesaid into action; and (d) a releasing means, whereby the motor-controlling device aforesaid is permitted to return toward its normal position in advance of the release of the key aforesaid; all the parts being constructed, arranged and operating in such a manner that when the key aforesaid is depressed to print, another key can also be depressed to print, without waiting to release the key first depressed. 85
9. A type-writing mechanism, including, in combination, (a) a key; (b) a motor; (c) a motor-controlling device; (d) a latch connecting said key with said motor-controlling device, and wherethrough said key, when depressed, gives movement to said motor-controlling device, to bring the motor aforesaid into action; and (e) means, acting upon said latch to release the motor-controlling device aforesaid, thereby to permit said motor-controlling device to return toward its normal position in advance of the release of the key aforesaid. 90

trolling device to return toward its normal position in advance of the release of the key controlling it.

10. A type-writing mechanism, including, in combination, (a) a key; (b) a motor device, normally inactive; (c) a motor-controlling device actuated by the key aforesaid and serving, when thus actuated, to bring the motor device aforesaid into action; said motor device thereupon acting to release the motor-controlling device, actuated by the key aforesaid, from said key, thereby to permit said motor-controlling device to return toward its normal position in advance of the release of the key controlling it; whereby the motor device aforesaid is again caused to be inactive all the parts being constructed, arranged and operating in such a manner that when the key aforesaid is depressed to print, another key can also be depressed to print, without waiting to release the key first depressed.

11. A type-writing mechanism, including in combination, (a) a key; (b) motor mechanism; (c) a controlling device for said motor mechanism; (d) a releasable connection intermediate said motor-controlling device and the key aforesaid, wherethrough said key, when depressed, actuates said motor-controlling device to bring the motor mechanism aforesaid into action; and (e) a vibratory frame, normally stationary, but actuated by the motor mechanism aforesaid and serving, when said motor mechanism is brought into action, upon the depressing of the key aforesaid, to permit the return of the motor-controlling device aforesaid toward its normal position in advance of the release of the key, all the parts being constructed, arranged and operating in such a manner that when the key aforesaid is depressed to print, another key can also be depressed to print, without waiting to release the key first depressed.

12. A type-writing machine, including, in combination, (a) a key, (b) a circuit-controller, receiving movement therefrom; and (c) releasing means, whereby said circuit-controller is left free to return toward its normal position in advance of the release of the key aforesaid.

13. A type-writing machine, including, in combination, (a) a key, (b) a circuit-controller; (c) a latch wherethrough said key, when depressed, gives movement to said circuit-controller; and (d) a frame for acting on said latch to release the circuit-controller aforesaid, thereby to permit said circuit-controller to return toward its normal position in advance of the release of the key aforesaid.

14. A type-writing machine, including, in combination, (a) a key; (b) an electromagnet; (c) a circuit-controller, actuated by the key aforesaid and releasably connected therewith; said circuit-controller serving, when actuated by the key aforesaid, to cause an action of the electromagnet aforesaid; said electromagnet acting, on the depressing of the key aforesaid, to release the circuit-controller

aforesaid, to permit said circuit-controller to return toward its normal position in advance of the release of the key aforesaid, all the parts being constructed, arranged and operating in such a manner that when the key aforesaid is depressed to print, another key can also be depressed to print, without waiting to release the key first depressed.

15. A type-writing machine, including, in combination, (a) a key; (b) an electromagnet; (c) a circuit-closer for the electromagnet aforesaid; (d) a releasable connection intermediate said key and said circuit-closer, wherethrough said key, when depressed, gives movement to said circuit-closer to close the circuit of the electromagnet aforesaid; said magnet thereupon acting upon the releasable connection aforesaid to permit the return of the circuit-closer aforesaid toward its normal position, whereby the circuit of the electromagnet aforesaid is broken in advance of the release of the key controlling it.

16. In a type-writing machine and in combination, (a) a type-bar; (b) a key; (c) a type-bar-controlling member actuated by said key, and releasably connected therewith; and (d) motor mechanism brought into action by the key-actuated movement of the type-bar-controlling member aforesaid, and operating to impel the type-bar aforesaid and to release the type-bar-controlling member aforesaid, thereby to permit the return of said type-bar-controlling member toward its normal position in advance of the release of the key controlling it, and whereby the type-bar also is permitted to return toward its normal position in advance of the release of said key, all the parts being constructed, arranged and operating in such a manner that when the key aforesaid is depressed to print, another key can also be depressed to print, without waiting to release the key first depressed.

17. In a type-writing machine having a plurality of type-bars striking to a common printing-center, the combination of (a) a type-bar; (b) a key; (c) a motor device for impelling said type-bar, to cause it to print; (d) a motor-controlling device receiving movement from the key aforesaid, and serving, when said key is depressed, to bring the motor device aforesaid into action for the impelling of the type-bar aforesaid; and (e) releasing means for the motor-controlling device aforesaid, whereby said motor-controlling device is left free to return toward its normal position in advance of the release of the key depressed.

18. In a type-writing machine having a plurality of type-bars striking to a common printing-center, the combination of (a) a type-bar; (b) a key; (c) a motor device for impelling said type-bar, to cause it to print; (d) a motor-controlling device; (e) a releasable connection intermediate said key and said motor-controlling device, wherethrough said key, when depressed, actuates said motor-controlling device; said motor-controlling de-

vice operating, when thus actuated, to bring the motor device aforesaid into action for the impelling of the type-bar aforesaid; said motor device also acting upon the releasable connection aforesaid to permit the return of the motor-controlling device aforesaid toward its normal position, whereby the power is cut off automatically from said motor device, and the type-bar left free to return toward its normal position in advance of the release of the key, all the parts being constructed, arranged and operating in such a manner that when the key aforesaid is depressed to print, another key can also be depressed to print, without waiting to release the key first depressed.

19. In a type-writing machine having a plurality of type-bars striking to a common printing-center, the combination of (a) a type-bar; (b) a key; (c) a motor device for impelling said type-bar, to cause it to print; (d) a motor-controlling device; (e) a latch intermediate said motor-controlling device and said key, wherethrough said key, when depressed, gives movement to said motor-controlling device; said motor-controlling device operating, when thus actuated, to bring the motor device aforesaid into action to impel the type-bar aforesaid; and (f) a pivoted frame, impelled by the motor device aforesaid, and acting upon the latch aforesaid to permit the return of the motor-controlling device aforesaid toward its normal position in advance of the release of the key aforesaid.

35 20. In a type-writing machine and in combination, (a) a type-bar; (b) a key; (c) an electromagnet serving to actuate said type-bar; (d) a circuit-controller for said electromagnet, actuated by the key aforesaid when said key is depressed; and (e) releasing means, whereby the circuit-controller aforesaid is left free to return toward its normal position in advance of the release of the key aforesaid, thereby to release the type-bar aforesaid, all the parts being constructed, arranged and operating in such a manner that when the key aforesaid is depressed to print, another key can also be depressed to print, without waiting to release the key first depressed.

50 21. In a type-writing machine and in combination, (a) a type-bar; (b) a key; (c) an electromagnet serving to actuate said type-bar; (d) a circuit-closer for the electromagnet aforesaid; (e) a latch intermediate the key aforesaid and the circuit-closer aforesaid, wherethrough said key, when depressed, gives movement to the circuit-closer aforesaid, so that it closes the circuit of the electromagnet aforesaid; and (f) a frame for acting on said latch, to permit the circuit-closer aforesaid to return toward its normal position, breaking the circuit of the type-bar-impelling magnet aforesaid in advance of the release of the key aforesaid.

65 22. In a type-writing machine and in combination, (a) a type-bar; (b) a key; (c) an electromagnet for actuating said type-bar; (d)

a circuit-controller actuated by the key aforesaid, and releasably connected therewith; said circuit-controller serving, when thus actuated, to cause the electromagnet aforesaid to give movement to the type-bar aforesaid; said electromagnet acting also to release the circuit-controller aforesaid, permitting it to return toward its normal position in advance 75 of the release of the key aforesaid, whereby the type-bar is released in advance of the release of said key, all the parts being constructed, arranged and operating in such a manner that when the key aforesaid is depressed to print, another key can also be depressed to print, without waiting to release the key first depressed.

23. In a type-writing machine and in combination, (a) a type-bar; (b) a key; (c) an electromagnet for actuating said type-bar; (d) a circuit-closer for said electromagnet; (e) a releasable connection intermediate said key and said circuit-closer wherethrough said key, when depressed, gives movement to said circuit-closer to close the circuit of the electromagnet aforesaid; and (f) a pivoted frame actuated by the electromagnet aforesaid and acting upon the releasable connection aforesaid to permit the circuit-closer aforesaid to return toward its normal position, breaking the circuit of the electromagnet aforesaid, in advance of the release of the key.

24. In a type-writing machine and in combination, (a) a key; (b) a normally-stationary intermittently-vibratory motor device; (c) spacing mechanism actuated by said motor device, whereby the letter-spaces are caused to be produced; (d) a motor-controlling device receiving movement from the key aforesaid and serving, when said key is depressed, to bring the motor device aforesaid into action to operate the spacing mechanism aforesaid; and (e) tripping means whereby the motor-controlling device aforesaid is permitted to return toward its normal position in advance of the release of the key aforesaid, thereby releasing the spacing mechanism aforesaid.

25. In a type-writing machine and in combination, (a) a key; (b) a normally-stationary intermittently-vibratory motor device; (c) spacing mechanism actuated by said motor device, whereby the letter-spaces are caused to be produced; (d) a motor-controlling device for the motor aforesaid; (e) a releasable connection intermediate said key and said motor-controlling device wherethrough, when said key is depressed, movement is communicated to said motor-controlling device to bring the motor aforesaid into action to operate the spacing mechanism aforesaid; and (f) a vibratory releasing-frame, normally stationary, but controlled by the key aforesaid, and serving, when said key is depressed, to act upon the releasable connection aforesaid, thereby to permit the motor-controlling device aforesaid to return toward its normal position in advance of the release of the key aforesaid.

26. A type-writing machine, including, in combination, (a) a key; (b) spacing mechanism whereby the letter-spaces are caused to be produced as the printing of a line progresses; (c) an electromagnet for actuating said spacing mechanism; (d) a circuit-controller for said electromagnet, operated by the key aforesaid when said key is depressed, said circuit-controlling device being normally in a position to render said electromagnet inactive, and tending when moved from its normal position to return thereto; and (e) releasing means, whereby said circuit-controller is left free to return toward its normal position in advance of the release of the key aforesaid. 75
27. A type-writing machine, including, in combination, (a) a key; (b) spacing mechanism whereby the letter-spaces are caused to be produced as the printing of a line progresses; (c) an electromagnet for actuating said spacing mechanism; (d) a circuit-controller for said electromagnet; (e) a releasable connection intermediate the key aforesaid and the circuit-controller aforesaid, where- 80
- 25 through said key, when depressed, gives movement to said circuit-controller; and (f) another electromagnet whose circuit is also controlled by the circuit-controller aforesaid, acting upon the releasable connection aforesaid to permit the return of the circuit-controller aforesaid toward its normal position in advance of the release of the key aforesaid. 85
28. In a type-writing machine, having a plurality of type-bars striking to a common printing-center, and in combination, (a) a type-bar; (b) a key; (c) a motor device for impelling said type-bar to cause it to print; (d) a motor-controlling device actuated by the key aforesaid and serving, when said key is de- 90
- 35 pressed, to bring the motor aforesaid into action for the impelling of the type-bar aforesaid; (e) letter-spacing mechanism, controlled by the motor-controlling device aforesaid; and (f) releasing means whereby the motor- 95
- 40 controlling device aforesaid is left free to return toward its normal position in advance of the release of the key depressed, all the parts being constructed, arranged and operating in such a manner that when the key aforesaid is depressed to print, another key can also be depressed to print, without waiting to release the key first depressed. 100
29. In a type-writing machine having a plurality of type-bars striking to a common printing-center, and in combination, (a) a type-bar; (b) a key; (c) a motor device for impelling said type-bar to cause it to print; (d) a motor-controlling device actuated by the key aforesaid and serving, when said key is de- 105
- 45 pressed, to bring the motor aforesaid into action for the impelling of the type-bar aforesaid; (e) letter-spacing mechanism, controlled by the motor-controlling device aforesaid; and (f) releasing mechanism also controlled by the motor-controlling device aforesaid; said releasing mechanism operating when the key aforesaid is depressed to permit the motor- 110
- 50
- 55
- 60
- 65

controlling device aforesaid to return toward its normal position in advance of the release of the key aforesaid, all the parts being constructed, arranged and operating in such a manner that when the key aforesaid is depressed to print, another key can also be depressed to print, without waiting to release the key first depressed. 115

30. In a type-writing machine and in combination, (a) a key; (b) a type-bar; (c) an electromagnet for actuating said type-bar; (d) a circuit-controller for said electromagnet, said circuit-controller receiving movement from the key aforesaid when said key is depressed; (e) a paper-carrier; (f) letter-spacing mechanism, controlled by the action of the circuit-controller aforesaid; and (g) releasing means whereby the circuit-controller aforesaid is permitted to return toward its normal position in advance of the release of the key aforesaid. 120

31. In a type-writing machine and in combination, (a) a key; (b) a type-bar; (c) an electromagnet for actuating said type-bar; (d) a paper-carrier; (e) letter-spacing mechanism therefor; (f) another electromagnet for actuating said letter-spacing mechanism; (g) a circuit-controlling device actuated by the key aforesaid when said key is depressed, and serving to control the two electromagnets aforesaid; and (h) means whereby the circuit-controlling device aforesaid is permitted to return toward its normal position in advance of the release of the key aforesaid. 125

32. In a type-writing machine, and in combination, (a) a type-bar; (b) a key; (c) a lever corresponding to and actuated by said key; (d) a type-bar-impelling motor, letter-spacing mechanism, and releasing mechanism, all controlled by said lever; said releasing mechanism acting, when the key aforesaid is depressed, to permit the key-actuated lever aforesaid to return toward its normal position in advance of the release of the key aforesaid. 130

33. In a type-writing machine and in combination, (a) a key; (b) a type-bar; (c) a letter-spacing device; (d) a vibratory releaser, normally stationary; (e) motor mechanism for impelling the type-bar aforesaid and for operating the letter-spacing device and the vibratory releaser aforesaid; (f) a member controlling said motor mechanism, said member being actuated by the key aforesaid; the vibratory releaser aforesaid operating to permit the key-actuated member aforesaid to return toward its normal position in advance of the release of said key, all the parts being constructed, arranged and operating in such a manner that when the key aforesaid is depressed to print, another key can also be depressed to print, without waiting to release the key first depressed. 135

34. In a type-writing machine and in combination, (a) a key; (b) a type-bar; (c) a letter-spacing device; (d) a releasing device; (e) electrically-controlled means for actuating

the type-bar aforesaid, and also for actuating the spacing device aforesaid and the releasing device aforesaid; and (f) circuit-controlling means receiving movement from the key aforesaid and acting, when said key is depressed, to cause the actuating of the type-bar aforesaid, the spacing device aforesaid and the releasing device aforesaid; said releasing device thereupon acting to permit the return of the circuit-controlling means actuated by the key aforesaid toward its normal position in advance of the release of said key.

35. In a type-writing machine and in combination, (a) a key; (b) a type-bar; (c) a type-bar-impelling frame; (d) letter-spacing mechanism; (e) a vibratory releaser, normally stationary; (f) a circuit-closing frame operated by the key aforesaid and releasably connected therewith; said circuit-closing frame tending when moved from its normal position, to return thereto; and (g) means, controlled by said circuit-closing frame, for actuating the type-bar-impelling frame, the spacing mechanism and the vibratory releaser aforesaid; the vibratory releaser aforesaid acting to permit the circuit-closing frame aforesaid to return toward its normal position in advance of the release of the key aforesaid.

36. In a type-writing machine and in combination, (a) a type-bar; (b) a vibratory motor device for impelling said type-bar; said type-bar being normally disconnected from said motor device; (c) a key; (d) means operated by said key for connecting said type-bar with said motor device when said key is depressed; and (e) releasing means, whereby said type-bar is disconnected from said motor device in advance of the release of the key aforesaid, all the parts being constructed, arranged and operating in such a manner that when the key aforesaid is depressed to print, another key can also be depressed to print, without waiting to release the key first depressed.

37. In a type-writing machine and in combination, (a) a type-bar; (b) a normally-stationary intermittently-vibratory motor device serving to impel said type-bar, said type-bar being normally disconnected from said motor device; (c) a key; (d) means operated by said key for connecting said type-bar with said motor device when said key is depressed; (e) a motor-controlling device actuated by the key aforesaid, when said key is depressed, and serving when thus actuated to bring the motor device aforesaid into action for the impelling of the type-bar aforesaid; said motor-controlling device tending when moved from its normal position on the depressing of a key, to return thereto; and (f) releasing means whereby said motor-controlling device is left free to return toward its normal position in advance of the release of the key aforesaid.

38. In a type-writing machine and in combination, (a) a type-bar; (b) a motor device serving to impel said type-bar; said type-bar being normally disconnected from said motor

device; (c) a key; (d) a type-bar-controlling lever corresponding to said key and receiving movement therefrom when said key is depressed; (e) means operated by said lever for connecting the type-bar aforesaid with the motor device aforesaid, and for bringing said motor device into action for impelling said type-bar when the key aforesaid is depressed; and (f) releasing means whereby the type-bar-controlling lever aforesaid is left free to return toward its normal position in advance of the release of the key controlling it.

39. In a type-writing machine and in combination, (a) a type-bar; (b) a vibratory type-bar-impelling frame normally stationary, the type-bar aforesaid being normally disconnected from said frame; (c) a key; (d) means operated by said key for connecting the type-bar aforesaid with the type-bar-impelling frame aforesaid when said key is acted on; (e) means, also controlled by the key aforesaid, acting, when said key is depressed, to actuate the type-bar-impelling frame aforesaid; and (f) means whereby the type-bar-impelling frame and the type-bar aforesaid are permitted to return toward their normal positions in advance of the release of the key aforesaid, and whereby the type-bar aforesaid is disconnected from the type-bar-impelling frame aforesaid in advance of the release of the key aforesaid, controlling it, all the parts being constructed, arranged and operating in such a manner that when the key aforesaid is depressed to print, another key can also be depressed to print, without waiting to release the key first depressed.

40. In a type-writing machine and in combination, (a) a type-bar; (b) a vibratory type-bar-impelling frame normally stationary, the type-bar aforesaid being normally disconnected from said frame; (c) a lever and means controlled thereby, serving when said lever is actuated, both to connect the type-bar aforesaid with the type-bar-impelling frame aforesaid, and to vibrate said frame to give movement to said type-bar; (d) a key acting when depressed to give movement to said lever; and (e) releasing means whereby said lever, when actuated by said key is left free to return toward its normal position in advance of the release of the said key.

41. In a type-writing machine and in combination, (a) a type-bar; (b) a vibratory type-bar-impelling frame normally stationary, the type-bar aforesaid being normally disconnected from said frame; (c) letter-spacing mechanism; (d) a releasing-frame; (e) means for connecting the type-bar aforesaid with the type-bar-impelling frame aforesaid; (f) motor mechanism for actuating the type-bar-impelling frame aforesaid, the letter-spacing mechanism, and the releasing-frame aforesaid; (g) a key; (h) means operated by said key, serving to connect the type-bar aforesaid with the type-bar-impelling frame aforesaid; (i) motor-controlling means whereby the motor mechanism aforesaid is brought

into action to impel the type-bar-impelling frame, the spacing mechanism, and the releasing-frame aforesaid; (k) a releasable connection intermediate the key aforesaid and the motor-controlling means aforesaid where-through said key, when depressed, actuates said motor-controlling means; the releasing-frame aforesaid acting upon said releasable connection to permit the motor-controlling means aforesaid to return toward its normal position in advance of the release of said key, all the parts being constructed, arranged and operating in such a manner that when the key aforesaid is depressed to print, another key can also be depressed to print, without waiting to release the key first depressed.

42. In a type-writing machine and in combination, (a) a type-bar; (b) a vibratory type-bar-impelling frame normally stationary, the type-bar aforesaid being normally disconnected from said frame; (c) letter-spacing mechanism; (d) a releasing-frame; (e) motor mechanism for actuating the type-bar-impelling frame aforesaid, the letter-spacing mechanism, and the releasing-frame aforesaid; (f) a motor-controlling device whereby the motor mechanism aforesaid is brought into action to impel the type-bar-impelling frame aforesaid, the letter spacing mechanism aforesaid and the releasing mechanism aforesaid; (g) a lever for operating said motor-controlling device, and means connected with said lever whereby the type-bar aforesaid is brought into operative relation with the type-bar-impelling frame aforesaid to receive movement therefrom; (h) a key, releasably connected with said lever, and operating when depressed to actuate the same; said lever thereupon operating both to bring the type-bar aforesaid into operative relation with the type-bar-impelling frame aforesaid, and also by its action upon the motor-controlling device aforesaid, serving to cause the motor mechanism aforesaid to actuate the type-bar-impelling frame aforesaid, the letter-spacing mechanism aforesaid and the releasing-frame aforesaid; said releasing-frame thereupon acting upon the releasable connection aforesaid to permit the return of the parts aforesaid controlled by the key aforesaid, to their normal positions in advance of the release of said key, all the parts being constructed, arranged and operating in such a manner that when the key aforesaid is depressed to print, another key can also be depressed to print, without waiting to release the key first depressed.

43. In a type-writing machine and in combination, (a) a type-bar; (b) a type-bar-impelling frame normally at rest, the type-bar aforesaid being normally disconnected from said frame; (c) an electromagnet for actuating said frame; (d) a key; (e) means controlled by said key, whereby the type-bar aforesaid is brought into operative relation with the type-bar-impelling frame aforesaid, to receive movement therefrom when the key aforesaid is depressed; (f) a circuit-controller actuated by

the key aforesaid, and serving to control the electromagnet aforesaid; and (g) releasing means, whereby said circuit-controller, when actuated by the key aforesaid, is left free to return toward its normal position in advance of the release of the key aforesaid.

44. In a type-writing machine and in combination, (a) a type-bar; (b) a type-bar-impelling frame, normally at rest, the type-bar aforesaid being normally disconnected from said frame; (c) an electromagnet for actuating said frame; (d) a lever and means operated thereby, whereby the type-bar aforesaid is brought into operative relation with the type-bar-impelling frame aforesaid to receive movement therefrom and whereby the electromagnet aforesaid is caused to actuate said frame for the impelling of said type-bar; (e) a key for giving movement to said lever; and (f) releasing means whereby said lever is left free to return toward its normal position in advance of the release of the key aforesaid, said circuit-controller tending when moved from its normal position by the key aforesaid, to return thereto thereby to permit the type-bar and type-bar-impelling frame aforesaid to return toward their normal positions without waiting for the key aforesaid, controlling them, to be released.

45. In a type-writing machine and in combination, (a) a type-bar; (b) a type-bar-impelling frame, normally at rest, the type-bar aforesaid being normally disconnected from said frame; (c) letter-spacing mechanism; (d) a vibratory releaser; (e) electromagnetic motor mechanism for actuating said type-bar-impelling frame, the letter-spacing mechanism, and the vibratory releaser aforesaid; (f) a lever, and means operated thereby whereby the type-bar aforesaid is brought into operative relation with the type-bar-impelling frame aforesaid, to receive movement therefrom, and whereby the electromagnetic motor mechanism aforesaid is brought into operation to actuate the type-bar-impelling frame, the letter-spacing mechanism and the vibratory releaser aforesaid; (g) a key; and (h) a connection intermediate said key and the lever aforesaid, wherethrough said key when depressed actuates said lever; the vibratory releaser aforesaid acting upon said connection to permit the lever aforesaid, controlling the motor mechanism aforesaid, to return toward its normal position, in advance of the release of the key.

46. In a type-writing machine, having a plurality of type-bars striking to a common printing-center, and in combination with said type-bars, type-bar-controlling mechanism including, (a) a plurality of keys; (b) type-bar-controlling elements, corresponding to the keys aforesaid, and each actuated by the corresponding key; and (c) a common releaser, controlled by the keys aforesaid, and acting, when a key is depressed to permit the type-bar-controlling element actuated by said key to return toward its normal position in ad-

vance of the release of said key, all the parts being constructed, arranged and operating in such a manner that when a key is depressed to print another key can also be depressed to print, without waiting to release the key first depressed.

47. In a type-writing machine having a plurality of type-bars striking to a common printing-center, and in combination, (a) a plurality of keys; (b) type-bar-controlling elements corresponding respectively to, and actuated respectively by, the keys aforesaid; (c) releasable connections intermediate said keys and said type-bar-controlling elements; and (d) a single vibratory releaser, for acting upon all said connections, each as required, to permit the type-bar-controlling element corresponding to a key depressed to return toward its normal position without waiting for such key to be released.

48. A type-selecting mechanism, including, in combination, (a) a plurality of keys; (b) levers corresponding to and actuated by the keys aforesaid; (c) latches connecting said keys with said levers, a latch for each key and lever; and (d) a releasing-frame for acting on a plurality of said latches, each latch as required.

49. In a type-writing machine having a plurality of type-bars striking to a common printing-center, and in combination with said type-bars, type-bar-controlling mechanism, including, (a) a plurality of keys; (b) type-bar-controlling elements corresponding to the keys aforesaid, and each actuated by the corresponding key; and (c) a motor device for tripping the type-bar-controlling elements aforesaid, and acting, when a key is depressed, to trip the type-bar-controlling element corresponding thereto, thereby to permit the making of a succeeding letter in advance of the release of the key previously depressed.

50. In a type-writing machine having a plurality of type-bars striking to a common printing-center, and in combination, (a) a plurality of keys; (b) type-bar-controlling elements corresponding respectively to and actuated respectively by the keys aforesaid; (c) releasable connections intermediate said keys and said type-bar-controlling elements; (d) a releasing-frame for acting on said releasable connections, each as required, to permit the type-bar-controlling element corresponding to the key depressed to return toward its normal position in advance of the release of said key; (e) another frame actuated by the keys aforesaid through the type-bar-controlling elements aforesaid; and (f) means controlled by the frame last mentioned for actuating the releasing-frame aforesaid.

51. In a type-writing machine having a plurality of type-bars striking to a common printing-center, and in combination, (a) a plurality of keys; (b) type-bar-controlling elements corresponding respectively to and actuated respectively by the keys aforesaid;

(c) releasable connections intermediate said keys and said type-bar-controlling elements; (d) a frame operated by the keys aforesaid through the type-bar-controlling elements aforesaid; and (e) a motor device controlled by said frame, and acting on the releasable connections aforesaid to release the type-bar-controlling elements aforesaid, each as required, to permit said type-bar-controlling elements and the motor-controlling frame operated therethrough to return to their normal positions in advance of the release of the key controlling them.

52. In a type-writing machine having a plurality of type-bars striking to a common printing-center, and in combination, (a) a plurality of keys; (b) type-bar-controlling elements corresponding to and actuated respectively by the keys aforesaid; (c) an electromagnet for tripping all the type-bar-controlling elements aforesaid, each as required; whereby when a key is depressed the type-bar-controlling element corresponding thereto is left free to return toward its normal position in advance of the release of said key, all the parts being constructed, arranged and operating in such a manner that when a key is depressed to print another key can also be depressed to print, without waiting to release the key first depressed.

53. In a type-writing machine having a plurality of type-bars striking to a common printing-center, and in combination, (a) a plurality of keys; (b) type-bar-controlling elements corresponding respectively to and actuated respectively by the keys aforesaid; (c) releasable connections intermediate said keys and said type-bar-controlling elements, a releasable connection intermediate said key and the corresponding type-bar-controlling element; (d) an electromagnet; (e) a circuit-controller operated by the type-bar-controlling elements aforesaid and controlling the electromagnet aforesaid; the electromagnet aforesaid acting, when a key is depressed, upon the connection aforesaid intermediate said key and the type-bar-controlling element operated by said key to permit said type-bar-controlling element and the circuit-closing frame aforesaid operated thereby, to return toward their normal positions in advance of the release of the key depressed.

54. In a type-writing machine having a plurality of type-bars striking to a common printing-center, and in combination, (a) a plurality of keys; (b) type-bar-controlling elements corresponding respectively to and actuated respectively by the keys aforesaid; (c) releasable connections intermediate said keys and said type-bar-controlling elements; (d) an electromagnet; (e) a circuit-controller operated by the type-bar-controlling elements aforesaid and controlling the electromagnet aforesaid; and (f) a frame, operated by the electromagnet aforesaid, and acting, when a key is depressed, upon the connection aforesaid intermediate said key and the type-bar-

controlling element operated by said key to permit said type-bar-controlling element and the circuit-closing frame aforesaid operated thereby, to return toward their normal positions in advance of the release of the key depressed, all the parts being constructed, arranged and operating in such a manner that when a key is depressed to print another key can also be depressed to print, without waiting to release the key first depressed.

55. A type-writing mechanism, including, in combination, (a) a plurality of keys; (b) a motor device normally inactive; (c) a motor-controlling device receiving movement from each of the keys aforesaid, and serving, when one of said keys is depressed, to bring the motor device aforesaid into action; and (d) a releasing means, whereby the motor-controlling device aforesaid is permitted to return toward its normal position, to stop the action of the motor device aforesaid in advance of the release of the key aforesaid.

56. A type-writing mechanism, including, in combination, (a) a plurality of keys; (b) a frame receiving movement from each of said keys; (c) a motor device controlled by said frame; and (d) releasing means whereby the frame aforesaid is permitted to return toward its normal position to cut off power from the motor device aforesaid in advance of the release of the key depressed.

57. A type-writing mechanism, including, (a) a plurality of keys; (b) levers, corresponding to and actuated by said keys; (c) latches connecting said keys with said levers; (d) a frame operated by the keys aforesaid through the levers aforesaid; and (e) a motor device controlled by the frame aforesaid, and serving to free the latches aforesaid.

58. A type-writing mechanism, including, (a) a plurality of keys; (b) a circuit-controller receiving movement from all said keys; (c) a tripping means whereby, when a key is depressed and the circuit-controller aforesaid operated thereby, said circuit-controller is left free to return toward its normal position in advance of the release of said key.

59. A type-writing mechanism, including, (a) a plurality of keys; (b) levers corresponding to said keys; (c) a circuit-controlling frame operated by said levers; (d) releasable connections intermediate said keys and said levers wherethrough said keys, when depressed, actuate said levers and the circuit-controlling frame aforesaid; (e) a releasing-frame for acting on the releasable connections aforesaid; and (f) a magnet controlled by the circuit-controlling frame aforesaid, and serving to actuate the releasing-frame aforesaid, whereby, when a key is depressed, the lever aforesaid corresponding to said key and the circuit-controlling frame aforesaid, are left free to return to their normal positions in advance of the release of said key, all the parts being constructed, arranged and operating in such a manner that when a key is depressed to print another key can also be depressed to

print, without waiting to release the key first depressed.

60. In a type-writing machine and in combination, (a) a plurality of type-bars striking to a common printing-point; (b) a normally-stationary intermittently-vibrating single-motor device for impelling said type-bars, each as required; said type-bars being normally disconnected from said motor device; (c) keys; (d) means operated by said keys for connecting the type-bars aforesaid, each as required, with the motor device aforesaid; and (e) releasing means whereby a type-bar, connected with the motor device aforesaid upon the depressing of a key, is disconnected from said motor device in advance of the release of the key depressed, all the parts being constructed, arranged and operating in such a manner that when a key is depressed to print another key can also be depressed to print, without waiting to release the key first depressed.

61. In a type-writing machine and in combination, (a) a plurality of type-bars striking to a common printing-center; (b) a motor device for impelling the type-bars aforesaid, each as required; said type-bars being normally disconnected from said motor device; (c) keys; (d) means operated by said keys for connecting said type-bars with the motor device aforesaid, each type-bar as required; (e) a motor-controlling device, operated by a plurality of the keys aforesaid, and serving, when a key is depressed, to bring the motor device aforesaid into action, for the impelling of the type-bar corresponding to the key depressed; (f) releasing means whereby said motor-controlling device is left free, when a key is depressed, to return toward its normal position in advance of the release of said key; all the parts being constructed, arranged and operating in such a manner that when a key is depressed to print another key can be depressed to print without waiting to release the key first depressed.

62. In a type-writing machine and in combination, (a) a plurality of type-bars striking to a common printing-center; (b) a single-motor device normally at rest, serving to impel said type-bars, each as required; (c) keys; (d) type-bar-controlling levers receiving movement from said keys; (e) means operated by said levers for connecting the type-bars aforesaid, each as required, with the motor device aforesaid, and for bringing said motor device into action to impel the type-bar connected with it when a key is depressed; and (f) releasing means for the type-bar-controlling levers aforesaid, whereby said levers are left free to return toward their normal positions in advance of the release of the key controlling them, so that the key can be held down without interfering with the action of the succeeding key or keys.

63. In a type-writing machine and in combination, (a) a plurality of type-bars striking to a common printing-center; (b) a type-bar-

impelling frame normally stationary; the type-bars aforesaid being normally disconnected from said frame; (c) keys; (d) means operated by said keys for connecting the type-bars aforesaid with the type-bar-impelling frame aforesaid, each type-bar as required; (e) means, controlled by the keys aforesaid, acting, when a key is depressed, to give movement to the type-bar-impelling frame aforesaid for the actuating of the type-bar aforesaid; and (f) means whereby the type-bar-impelling frame and the type-bar actuated thereby are permitted to return toward their normal positions in advance of the release of the key aforesaid, and whereby the type-bar aforesaid is disconnected from the type-bar-impelling frame aforesaid in advance of the release of the key depressed to control it, all the parts being constructed, arranged and operating in such a manner that when a key is depressed to print another key can be depressed to print without waiting to release the key first depressed.

64. In a type-writing machine and in combination, (a) a plurality of type-bars striking to a common printing-center; (b) a vibratory type-bar-impelling frame, normally stationary; the type-bars aforesaid being normally disconnected from said frame; (c) keys; (d) type-bar-controlling levers receiving movement from said keys and releasably connected therewith; (e) means operated by the type-bar-controlling levers aforesaid, serving when a key is depressed to connect the appropriate type-bar with the type-bar-impelling frame aforesaid, to receive movement therefrom, and serving also to vibrate said frame to give movement to said type-bar; and (f) releasing means for the type-bar-controlling levers aforesaid, whereby each of said levers when actuated by the corresponding key, is left free to return toward its normal position in advance of the release of such key, whereby a key may be depressed to make a letter without first releasing the key or keys previously depressed.

65. In a type-writing machine and in combination, (a) a plurality of type-bars striking to a common printing-center; (b) a single-motor device for impelling the type-bars aforesaid, each as required; (c) keys; (d) type-bar-controlling elements corresponding to and actuated by said keys; each of said type-bar-controlling elements being releasably connected with the corresponding key, to receive movement therefrom when said key is depressed; (e) means operated by the type-bar-controlling elements aforesaid, whereby the type-bars aforesaid are connected, each as required, with the motor device aforesaid to receive movement therefrom; (f) a vibratory frame, operated by the type-bar-controlling elements aforesaid, and serving, when a key is depressed, to bring the motor device aforesaid into action to impel the type-bar connected with it; and (g) releasing means whereby the type-bar-controlling element corre-

sponding to the key depressed and actuated thereby is left free to return toward its normal position in advance of the release of such key, to permit the depressing of a subsequent key or keys to print without releasing the key first depressed.

66. In a type-writing machine and in combination, (a) a plurality of type-bars striking to a common printing-center; (b) a single-motor device for impelling the type-bars aforesaid, each as required; (c) keys; (d) type-bar-controlling elements corresponding to and actuated by said keys; each of said type-bar-controlling elements being releasably connected with the corresponding key, to receive movement therefrom when said key is depressed; (e) means operated by the type-bar-controlling elements aforesaid, whereby the type-bars aforesaid are connected, each as required, with the motor device aforesaid to receive movement therefrom; (f) a vibratory frame, operated by the type-bar-controlling elements aforesaid, and serving, when a key is depressed, to bring the motor device aforesaid into action to impel the type-bar connected with it; and (g) letter-spacing mechanism, controlled by the frame above mentioned as operated by the type-bar-controlling elements aforesaid; and (h) releasing means whereby the type-bar-controlling element corresponding to a key depressed and actuated thereby is left free to return toward its normal position in advance of the release of such key, to permit the depressing of a subsequent key or keys to print without releasing the key first depressed.

67. In a type-writing machine and in combination, (a) a plurality of type-bars striking to a common printing-center; (b) a type-bar-impelling frame for giving movement to said type-bars; said frame being normally stationary, and said type-bars being normally disconnected therefrom; (c) keys; (d) type-bar-controlling elements corresponding to and actuated by said keys; each of said type-bar-controlling elements being releasably connected with the corresponding key to receive movement therefrom when said key is depressed; (e) means operated by the type-bar-controlling elements aforesaid whereby the type-bars aforesaid are connected, each as required, with the type-bar-impelling frame aforesaid, to receive movement therefrom; (f) letter-spacing mechanism; (g) a releasing-frame; (h) motor mechanism for impelling the type-bar-impelling frame aforesaid, the letter-spacing mechanism aforesaid, and the releasing-frame aforesaid; said releasing-frame acting, when a key is depressed, to release the type-bar-controlling element corresponding to such key, thereby to permit the return of said type-bar-controlling element toward its normal position in advance of the release of the key depressed, whereby a subsequent key may be depressed to print without first releasing the key previously depressed.

68. In a type-writing machine and in combination, (a) a plurality of type-bars striking to a common printing-center; (b) a type-bar-impelling frame for giving movement to said type-bars; said frame being normally stationary, and said type-bars being normally disconnected therefrom; (c) keys; (d) levers corresponding to and actuated by said keys, each of said levers being releasably connected with the corresponding key to receive movement therefrom when said key is depressed; (e) means operated by the levers aforesaid whereby the type-bars aforesaid are connected, each as required, with the type-bar-impelling frame aforesaid to receive movement therefrom; (f) a releasing-frame; (g) a single-motor device for actuating both the type-bar-impelling frame aforesaid and the releasing-frame aforesaid; (h) a frame operated by the key-actuated levers aforesaid and means connected with said frame to control the motor mechanism aforesaid; (i) letter-spacing mechanism, controlled by the frame last mentioned, the releasing-frame above mentioned serving, when a key is depressed, to permit the return of the lever before mentioned as corresponding to said key and actuated thereby toward its normal position in advance of the release of said key; so that a subsequent key or keys may be depressed to print without releasing the key first depressed.

69. In a type-writing machine and in combination, (a) a plurality of type-bars striking to a common printing-center; (b) a type-bar-impelling frame normally at rest; the type-bars aforesaid being normally disconnected from said frame; (c) an electromagnet for actuating said frame; (d) keys; (e) means controlled by said keys whereby when a key is depressed the appropriate type-bar is brought into operative relation with the type-bar-impelling frame aforesaid, to receive movement therefrom; (f) a circuit-controller actuated by each of the keys aforesaid, controlling the electromagnet aforesaid; and (g) releasing means whereby said circuit-controller, when actuated by the depressing of a key, is left free to return toward its normal position in advance of the release of said key, all the parts being constructed, arranged and operating in such a manner that when a key is depressed to print another key can be depressed to print without waiting to release the key first depressed.

70. In a type-writing machine and in combination, (a) a plurality of type-bars striking to a common printing-center; (b) a type-bar-impelling frame normally at rest, the type-bars aforesaid being normally disconnected from the frame aforesaid; (c) type-bar-controlling elements and means operated thereby whereby the different type-bars aforesaid are connected with the type-bar-impelling frame aforesaid, each as required; (d) keys, releasably connected with said type-bar-controlling elements; (e) letter-spacing mechan-

ism; (f) a circuit-closing frame, actuated by the keys aforesaid through the type-bar-controlling elements aforesaid; (g) electromagnetic mechanism controlled by said circuit-closing frame for actuating the type-bar-impelling frame aforesaid and the letter-spacing mechanism aforesaid; and (h) releasing means whereby, when a key is depressed, the type-bar-controlling element aforesaid actuated by said key, is left free to return toward its normal position in advance of the release of said key, thereby to permit the printing of a subsequent letter or letters in advance of the release of the key first depressed.

71. In a type-writing machine and in combination, (a) a plurality of type-bars striking to a common printing-center; (b) a type-bar-impelling frame normally at rest; the type-bars aforesaid being normally disconnected from said frame; (c) keys; (d) levers actuated by said keys, and means controlled by said levers whereby the type-bars aforesaid are connected each as required, with the type-bar-impelling frame aforesaid; (e) releasable connections intermediate said keys and said levers; (f) letter-spacing mechanism; (g) a vibratory releaser, for acting on the releasable connections aforesaid; (h) a circuit-closing frame operated by the keys aforesaid through the key-actuated levers aforesaid; (i) electrical means controlled by said circuit-closing frame for actuating the type-bar-impelling frame aforesaid, the letter-spacing mechanism aforesaid, and the vibratory releaser aforesaid, when a key is depressed; the vibratory releaser aforesaid acting, when a key is depressed, upon the releasable connections intermediate said key and the key-actuated lever before mentioned corresponding to and actuated by said key, to permit said key-actuated lever to return toward its normal position in advance of the release of the key depressed; thereby to permit the printing of a subsequent letter in advance of the release of the key first depressed.

72. In a type-writing machine and in combination, (a) a plurality of type-bars striking to a common printing-center; (b) a type-bar-impelling frame normally at rest; the type-bars aforesaid being normally disconnected from said frame; (c) keys; (d) levers actuated by said keys, and means controlled by said levers whereby the type-bars aforesaid are connected, each as required, with the type-bar-impelling frame aforesaid; (e) latches intermediate said keys and said levers; (f) letter-spacing mechanism; (g) a pivoted releasing-frame for acting on the latches aforesaid; (h) a pivoted circuit-closing frame operated by the keys aforesaid through the key-actuated levers aforesaid; (i) electromagnetic means controlled by said circuit-closing frame for actuating the type-bar-impelling frame aforesaid, the letter-spacing mechanism aforesaid and the releasing-frame aforesaid when a key is depressed; the releasing-frame aforesaid acting, when a key

is depressed, upon the latch intermediate said key and the lever before mentioned as actuated by and releasably connected with said key, to permit said lever to return toward its 5 normal position in advance of the release of said key; whereby the printing of a subsequent letter is made possible without having first to release the key previously depressed.

73. In combination in a type-writing machine, (a) an alphabet of type-bars striking to a common printing-center; (b) members fewer in number than said type-bars, and means, controlled by said members acting singly and in different combinations, for actuating said type-bars, each as required; (c) keys, corresponding to and controlling said members; and (d) releasing means for the members aforesaid, operating, when a key is depressed, to permit that one of the members 20 aforesaid corresponding to and controlled by the key depressed, to return toward its normal position in advance of the release of said key, whereby another key may be depressed to print while the key first depressed is still 25 held down.

74. In combination in a type-writing machine, (a) an alphabet of type-bars striking to a common printing-center; (b) members, fewer in number than said type-bars, and 30 means, controlled by said members for actuating said type-bars, each as required; (c) keys, corresponding to and controlling said members; (d) latches, intermediate said keys and said members, a latch for each key and 35 the corresponding member; and (e) a releaser, common to a plurality of said latches, and serving, when a key is depressed, to act upon the latch corresponding to said key to permit the member aforesaid corresponding to said 40 key to return toward its normal position in advance of the release of said key, whereby another key may be depressed to print while the preceding key is still held down.

75. In combination in a type-writing machine, (a) an alphabet of type-bars striking to a common printing-center; (b) members fewer in number than said type-bars, and means, controlled by said members acting singly and in different combinations, for actuating said type-bars, each as required; (c) keys, corresponding to and controlling said members; (d) connections intermediate said keys and said members; (e) a motor; and (f) a controlling device for said motor, said controlling device being operated by the keys aforesaid through the members aforesaid; said motor acting, when a key is depressed, upon the connection intermediate said key and the member aforesaid controlled thereby, 55 to permit said member to return toward its normal position in advance of the release of said key, whereby another key may be depressed to print while the key first depressed is still held down.

65 76. In combination in a type-writing machine, (a) an alphabet of type-bars striking to a common printing-center; (b) members,

fewer in number than said type-bars, and means, controlled by said members, for actuating said type-bars, each as required; (c) 70 keys, corresponding to and controlling said members; (d) latches, intermediate said keys and said members, a latch for each key and the corresponding member; (e) a releasing-frame, common to a plurality of said latches; 75 and (f) an electromagnet for actuating said releasing-frame; said frame acting, when a key is depressed, upon the latch corresponding to said key, to permit the member operated by said key through said latch to return 80 toward its normal position in advance of the release of said key, whereby another key may be depressed to print while the key first depressed is still held down.

77. In combination in a type-writing machine, (a) an alphabet of type-bars striking to a common printing-center; (b) members fewer in number than said type-bars, and means, controlled by said members, for actuating said type-bars, each as required; (c) 85 keys, corresponding to and controlling said members; (d) releasable connections intermediate said keys and said members; (e) an electromagnet for freeing a plurality of said releasable connections; (f) a circuit-controller 90 for said magnet, operated by the keys aforesaid through the members aforesaid, whereby when a key is depressed, the magnet aforesaid is brought into action to free the releasable connection between said key and the member aforesaid corresponding to and controlled by said key, to permit said member to return toward its normal position in advance of the release of said key, whereby another key may be depressed to print while the key first 95 depressed is still held down.

78. In combination in a type-writing machine, (a) a plurality of type-bars, striking to a common printing-center; (b) a device controlling said type-bars; (c) a key, for operating said type-bar-controlling device; (d) a latch, intermediate said key and said type-bar-controlling device; and (e) means, acting, when said key is depressed, upon said latch, to permit the type-bar-controlling device aforesaid to return toward its normal position in advance of the release of said key, all the parts being constructed, arranged and operating in such a manner that when the key aforesaid is depressed to print, another 100 key can also be depressed to print, without waiting to release the key first depressed.

79. In combination in a type-writing machine, (a) a plurality of type-bars striking to a common printing-center; (b) a member 105 wherefrom movement is communicated to said type-bars, each as required, and means whereby said member is made to operate the different type-bars aforesaid, each as required; (c) a motor for actuating said member; (d) 110 a device controlling the action of said motor upon said member; (e) a key at the keyboard, serving, when depressed, to actuate the motor-controlling device aforesaid, thereby to cause 115

- the motor aforesaid to operate the member aforesaid, and one of the type-bars controlled thereby; and (f) releasing means, whereby said motor-controlling device is left free to 5 return toward its normal position in advance of the release of the key depressed, all the parts being constructed, arranged and operating in such a manner that they allow of the depressing of a subsequent key to print while 10 the key first depressed is still held down.
80. In combination in a type-writing machine, (a) a plurality of type-bars striking to a common printing-center; (b) a member wherefrom movement is communicated to said 15 type-bars, each as required, and means whereby said member is made to operate the different type-bars aforesaid, each as required; (c) a motor for actuating said member; (d) a device controlling the action of said motor 20 upon said member; (e) a key at the keyboard; (f) a latch wherethrough said key actuates the motor-controlling device aforesaid to cause the motor aforesaid to actuate the member aforesaid and one of the type-bars operated 25 by it; (g) means operated by the motor-controlling device aforesaid for freeing said latch to permit the return of the motor-controlling device aforesaid and the parts controlled thereby, toward their normal positions, in ad- 30 vance of the release of the key depressed, all the parts being constructed, arranged and operating in such a manner that they allow of the depressing of a subsequent key to print while the key first depressed is still held down.
81. In combination in a type-writing machine, (a) a plurality of groups of type-bars striking to a common printing-center; (b) devices, each controlling a different group of 35 said type-bars; (c) keys, corresponding to 40 said group-controlling devices; (d) latches intermediate said keys and said group-controlling devices, a latch for each key and the corresponding group-controlling device; and (e) means, acting when a key is depressed, 45 upon the latch corresponding to said key, to permit the corresponding group-controlling device to return toward its normal position in 50 advance of the release of said key, whereby the key first depressed is still held down.
82. In combination in a type-writing machine, (a) a plurality of groups of type-bars striking to a common printing-center; (b) members, each controlling a different group 55 of said type-bars; (c) means whereby the different type-bars of a group controlled by one of the members aforesaid are brought into operative relation with said member to receive movement therefrom, each type-bar as required; (d) a motor for actuating a plurality of said group-controlling members; (e) devices for bringing said group-controlling members into operative relation, each as required, with the motor device aforesaid, to 60 receive movement therefrom; (f) keys, actuating the devices last mentioned; and (g) releasing means, whereby when a key is de- 65

pressed the device aforesaid actuated by said key to bring the corresponding group-controlling member into operative relation with the motor aforesaid, is released in advance of the release of the key depressed, so that another key may be depressed to print while the key first depressed is still held down.

83. In combination in a type-writing machine, (a) a plurality of groups of type-bars striking to a common printing-center; (b) members, each controlling a different group of said type-bars; (c) means whereby the different type-bars of a group, controlled by one of the members aforesaid, are brought into operative relation with said member to receive movement therefrom, each type-bar as required; (d) a motor for actuating a plurality of said group-controlling members; (e) devices for bringing said group-controlling members into operative relation, each as required, with the motor device aforesaid, to receive movement therefrom; (f) keys, actuating the devices last mentioned; (g) latches intermediate said keys and said devices, a latch for each key and the corresponding device actuated thereby; and (h) motor-operated means acting, when a key is depressed, to free the latch aforesaid corresponding to said key, thereby to permit another key to be depressed to print while the key first depressed is still held down.

84. In combination in a type-writing machine, (a) a plurality of groups of type-bars striking to a common printing-center; (b) members, each controlling a different group of said type-bars; (c) means whereby the different type-bars of a group, controlled by one of the members aforesaid, are brought into operative relation with said member to receive movement therefrom, each type-bar as required; (d) a vibratory frame normally stationary, for actuating a plurality of said group-controlling members, each as required; (e) devices, for bringing said group-controlling members into operative relation with said frame, each as required, to receive movement from said frame; (f) keys, actuating the devices last mentioned; (g) releasing means, whereby when a key is depressed, the device aforesaid, actuated by said key to bring the corresponding one of the group-controlling members aforesaid into operative relation with the vibratory frame aforesaid, is released in advance of the release of the key depressed, to permit another key to be depressed to print while the key first depressed is still held down.

85. In combination in a type-writing machine, (a) a plurality of groups of type-bars striking to a common printing-center; (b) members, each controlling a different group of said type-bars; (c) means whereby the different type-bars of a group, controlled by one of the members aforesaid, are brought into operative relation with said member to receive movement therefrom, each type-bar as required; (d) a vibratory frame normally sta-

tionary, for actuating a plurality of said group-controlling members, each as required; (e) devices, for bringing said group-controlling members into operative relation with said frame, each as required, to receive movement from said frame; (f) keys, actuating the devices last mentioned; (g) a motor for actuating the frame aforesaid; (h) a device controlling the action of said motor upon said frame; (i) means, acting when a key is depressed and the corresponding type-bar set in motion by the means aforesaid, to permit the motor-controlling device aforesaid, the vibratory frame aforesaid, and the group-controlling member and type-bar operated thereby, to return toward their normal positions in advance of the release of the key depressed, whereby another key may be depressed while the key first depressed is still held down.

86. In combination in a type-writing machine, (a) a plurality of groups of type-bars striking to a common printing-center; (b) members, each controlling a different group of said type-bars; (c) means whereby the different type-bars of a group controlled by one of the members aforesaid, are brought into operative relation with said member to receive movement therefrom, each type-bar as required; (d) a vibratory frame normally stationary, for actuating a plurality of said group-controlling members, each as required; (e) devices, for bringing said group-controlling members into operative relation with said frame, each as required, to receive movement from said frame; (f) keys, actuating the devices last mentioned; (g) an electromagnet for actuating the frame aforesaid; (h) a circuit-controlling device for said magnet, operated by the keys aforesaid; and (i) means acting, when a key is depressed and the corresponding type-bar set in motion toward the printing-point, to release the circuit-controlling device aforesaid, the vibratory frame aforesaid and the group-controlling member and type-bar operated thereby, to permit said parts to return toward their normal positions in advance of the release of the key depressed, whereby another key may be depressed while the key first depressed is still held down.

87. In a type-writing machine, an alphabet of type-bars striking to a common printing-center, in combination with type-bar-selecting mechanism having keys fewer in number than the letters of the alphabet and means, operated by said keys, whereby the operator is enabled to control all the letters of the alphabet, each as required, by acting upon the keys aforesaid singly and in different combinations, said means including, (a) levers, corresponding to said keys, and each operated by the key to which it corresponds; (b) means, operated by said key-corresponding levers, for actuating the type-bars aforesaid, each as required; and (c) releasing means, whereby, when a combination of keys is depressed the key-corresponding levers operated there-

by are released simultaneously in advance of the release of said keys, so that another key or combination of keys may be depressed to print while the key or combination of keys first depressed is still held down.

88. In a type-writing machine, an alphabet of type-bars striking to a common printing-center in combination with type-bar-selecting mechanism having keys fewer in number than the letters of the alphabet, and means operated by said keys, whereby the operator is enabled to control all the letters of the alphabet, each as required, by acting upon the keys aforesaid, singly and in different combinations, said means including, (a) levers, corresponding to said keys and actuated thereby; (b) latches, intermediate said keys and said levers, a latch for each key and the corresponding lever; (c) means, operated by said key-corresponding levers for actuating the type-bars aforesaid, each as required; and (d) a vibratory releasing-frame, acting, when a combination of keys is depressed, upon the latches corresponding to said keys, to permit the key-corresponding levers operated by said keys to return toward their normal positions in advance of the release of the keys depressed.

89. In a type-writing machine, an alphabet of type-bars striking to a common printing-center in combination with type-bar-selecting mechanism having keys fewer in number than the letters of the alphabet, and means operated by said keys, whereby the operator is enabled to control all the letters of the alphabet, each as required, by acting upon the keys aforesaid, singly and in different combinations, said means including, (a) levers, corresponding to said keys and actuated thereby; (b) latches, intermediate said keys and said levers, a latch for each key and the corresponding lever; (c) means, operated by said key-corresponding levers for actuating the type-bars aforesaid, each as required; (d) a releasing-frame, acting, when a combination of keys is depressed, upon the latches corresponding to said keys, to permit the key-corresponding levers operated by said keys to return toward their normal positions in advance of the release of the keys depressed; (e) a motor, for actuating said releasing-frame; and (f) a controlling device for said motor, operated by the keys aforesaid.

90. In a type-writing machine and in combination therein with a set of type-bars disposed about a circle, and striking to a common printing-center, a type-bar-selecting device, including an oscillating circular pin-carrier, having movement-transmitting pins mounted therein and supported thereby, and springs in said carrier for returning said pins to their normal positions.

91. In a type-writing machine and in combination therein with a set of type-bars disposed about a circle, and striking to a common printing-center, a type-bar-selecting device, including (a) an oscillating circular pin-

- carrier, having movement-transmitting pins mounted therein and supported thereby; (b) one or more keys for positioning said carrier; and (c) means for arresting said carrier.
5. 92. In a type-writing machine and in combination therein with a set of type-bars disposed about a circle and striking to a common printing-center, a type-bar-selecting device, including (a) an oscillating circular pin-carrier, having movement-transmitting pins mounted therein and supported thereby; (b) a plurality of keys for positioning said pin-carrier; and (c) stopping means for said pin-carrier, controlled by one or more of said keys.
15. 93. In a type-writing machine and in combination therein, with a set of type-bars disposed around a circle, and striking to a common printing-center, the levers 52, 52, connected with said type-bars; the group-controlling levers 65, 65 and an oscillating circular pin-carrier with movement-transmitting pins mounted therein and supported thereby, to travel intermediate the group-controlling levers aforesaid and the levers 52, 52.
25. 94. In combination in a type-writing machine, (a) a set of type-bars disposed about a circle, and striking to a common printing-center; (b) levers 52, 52, connected with said type-bars; (c) an oscillating circular pin-carrier with movement-transmitting pins mounted therein and supported thereby, for acting on the levers 52, 52 aforesaid; (d) segment-furnished group-controlling levers for actuating said pins; (e) one or more keys for positioning said circular pin-carrier; (f) other keys corresponding to the group-controlling levers aforesaid; and (g) means controlled by said keys for actuating said group-controlling levers, each as required.
35. 95. In combination in a type-writing machine, (a) a plurality of groups of type-bars disposed about a circle and striking to a common printing-center; (b) devices, each controlling a different group of said type-bars, (c) levers connected with said type-bars; (d) an oscillating circular pin-carrier with movement-transmitting pins mounted therein and supported thereby, to travel intermediate the group-controlling devices aforesaid and the type-bar-connected levers aforesaid, a pin for each group-controlling device, to bring said group-controlling device into operative relation with the different type-bar-connected levers operated by it, each as required.
45. 96. In combination in a type-writing machine (a) a plurality of groups of type-bars striking to a common printing-center; (b) devices, each controlling a different group of said type-bars; (c) levers connected with said type-bars; (d) an oscillating circular pin-carrier with movement-transmitting pins mounted therein and supported thereby, to travel intermediate the group-controlling devices aforesaid and the type-bar-connected levers aforesaid, a pin for each group-controlling device, to bring said group-controlling device into operative relation with the different type-bar-connected levers operated by it, each as required.
55. 97. In combination in a type-writing machine (a) a plurality of groups of type-bars striking to a common printing-center; (b) devices, each controlling a different group of said type-bars; (c) levers connected with said type-bars; (d) an oscillating circular pin-carrier with movement-transmitting pins mounted therein and supported thereby, to travel intermediate the group-controlling devices aforesaid and the type-bar-connected levers aforesaid, a pin for each group-controlling device, to bring said group-controlling device into operative relation with the different type-bar-connected levers operated by it, each as required; (e) one or more keys for positioning said pin-carrier; (f) a motor device for operating the group-controlling devices aforesaid, each as required; said group-controlling devices being normally disconnected from said motor device; and (g) keys, and means controlled thereby, whereby the group-controlling devices aforesaid are brought into operative relation with the motor device aforesaid, each group-controlling device as required, to receive movement therefrom, and whereby said motor device is brought into action to operate the group-controlling device brought into operative relation with it by the key depressed.
65. 98. In combination in a type-writing machine (a) a plurality of groups of type-bars striking to a common printing-center; (b) devices, each controlling a different group of said type-bars; (c) levers connected with said type-bars; (d) an oscillating circular pin-carrier with movement-transmitting pins mounted therein and supported thereby, to travel intermediate the group-controlling devices aforesaid and the type-bar-connected levers aforesaid, a pin for each group-controlling device, to bring said group-controlling device into operative relation with the different type-bar-connected levers operated by it, each as required; (e) one or more keys for positioning said pin-carrier; (f) a vibratory frame for giving movement to the group-controlling devices aforesaid, each as required; said vibratory frame being normally stationary and said group-controlling devices being normally disconnected from said frame; (g) keys and means controlled thereby, whereby the group-controlling devices aforesaid are brought into operative relation, each as required, with the vibratory frame aforesaid, to receive movement therefrom; and (h) a motor device, controlled by said keys, whereby the vibratory frame aforesaid is actuated when a key is depressed.
75. 99. In combination in a type-writing machine (a) a plurality of groups of type-bars

striking to a common printing-center; (b) devices, each controlling a different group of said type-bars; (c) levers connected with said type-bars; (d) an oscillating circular pin-carrier with movement-transmitting pins mounted therein and supported thereby, to travel intermediate the group-controlling devices aforesaid and the type-bar-connected levers aforesaid, a pin for each group-controlling device, to bring said group-controlling device into operative relation with the different type-bar-connected levers operated by it, each as required; (e) one or more keys for positioning said pin-carrier; (f) a vibratory frame for giving movement to the group-controlling devices aforesaid, each as required; said vibratory frame being normally stationary and said group-controlling devices being normally disconnected from said frame; (g) keys and means controlled thereby, whereby the group-controlling devices aforesaid are brought into operative relation, each as required, with the vibratory frame aforesaid, to receive movement therefrom; and (h) an electromagnet whereby the vibratory frame aforesaid is actuated when a key is depressed.

100. In a type-writing machine, the combination with the levers 65, 65, the vibratory frame for actuating said levers, and the movement-receiving arms pivoted to said levers to receive movement from said vibratory frame, of (a) bell-cranks connected with the movement-receiving arms aforesaid; (b) keys at the keyboard for actuating said bell-cranks; and (c) means controlled by said keys for actuating the vibratory frame aforesaid.

101. In a type-writing machine, the combination with a plurality of levers, a vibratory frame for actuating said levers, and the movement-receiving arms pivoted to said levers to receive movement from said vibratory frame, of (a) bell-cranks connected with the movement-receiving arms aforesaid; (b) levers, for giving movement to said bell-cranks; (c) keys, corresponding to the levers last mentioned; (d) latches intermediate said keys and the levers last aforesaid, a latch for each key and the corresponding lever; and (e) means operated by the levers last mentioned, for actuating the vibratory frame aforesaid, and for releasing the latches aforesaid.

102. In combination in a type-writing machine, (a) a plurality of groups of type-bars arranged about a circle and striking to a common printing-center; (b) levers 52, 52, corresponding to said type-bars and each connected with the corresponding type-bar; (c) group-controlling levers, each controlling a different group of the type-bars aforesaid; (d) an oscillating circular pin-carrier with movement-transmitting pins mounted therein, and supported thereby, to travel intermediate the group-controlling levers aforesaid and the type-bar-connected levers operated thereby; (e) one or more keys for positioning said pin-carrier; (f) a vibratory frame for

actuating said group-controlling levers; (g) arms pivoted to said levers to receive movement from said vibratory frame; (h) bell-cranks connected with said movement-receiving arms; (i) keys at the keyboard for actuating said bell-cranks; and (k) means controlled by said keys for actuating the vibratory frame aforesaid.

103. In combination in a type-writing machine (a) a plurality of groups of type-bars striking to a common printing-center; (b) levers 52, 52, corresponding to said type-bars and each connected with the corresponding type-bar; (c) group-controlling levers, each controlling a different group of the type-bars aforesaid; (d) an oscillating pin-carrier with movement-transmitting pins mounted therein and supported thereby, to travel intermediate the group-controlling levers aforesaid and the type-bar-connected levers aforesaid, operated thereby; (e) one or more keys for positioning said pin-carrier; (f) a vibratory frame for actuating said group-controlling levers; (g) arms pivoted to said group-controlling levers to receive movement from said vibratory frame; (h) bell-cranks connected with said movement-receiving arms; (i) levers, for giving movement to said bell-cranks; (k) keys at the keyboard corresponding to the levers last mentioned; (l) latches intermediate said keys and the levers last aforesaid; and (m) means operated by the last-mentioned levers, serving to actuate the vibratory frame aforesaid and to release the latches aforesaid.

104. In combination, in a keyboard printing instrumentality, (a) a key; (b) a type-controlling member, actuated by said key, and coming to rest when said key comes to rest in its depressed position; (c) a connection intermediate said key and said type-controlling member, wherethrough movement is communicated from said key to said type-controlling member; and (d) a part, set in motion in consequence of the depressing of said key, and acting, when said key has been depressed and is at rest in its depressed position and the type-controlling member aforesaid is at rest in the position into which it is moved by said key, upon the connection aforesaid, to disconnect the type-controlling member aforesaid from the key aforesaid, thereby to permit said type-controlling member to return toward its normal position in advance of the release of said key, whereby another key may be depressed while the key first depressed is held down.

105. In combination, in a keyboard printing instrumentality, (a) a key; (b) a type-selecting device; (c) a latch for connecting said key with said type-selecting device; and (d) a tripper controlled by the key aforesaid, and operating to free said latch, after the depressing of the key aforesaid and before the release thereof, whereby another key may be depressed in advance of the release of the key first depressed.

106. In combination, in a keyboard printing instrumentality, (a) a key; (b) a type-controlling member; (c) a releasable connection intermediate said key and said type-controlling member, wherethrough said key, when depressed, gives movement to said type-controlling member; and (d) a vibratory motor device, normally stationary, but controlled by the key aforesaid and acting, when said key is depressed upon the releasable connection aforesaid, to permit the type-controlling member aforesaid to return toward its normal position in advance of the release of the key aforesaid, whereby another key may be depressed while the key first depressed is still held down.

107. In combination, in a keyboard printing instrumentality, (a) a key; (b) a type-controlling member; (c) a latch for connecting said type-controlling member and key; (d) a releasing-frame, normally at rest, for acting upon said latch to permit the type-controlling member aforesaid to return toward its normal position in advance of the release of the key aforesaid; and (e) a motor device, controlled by the key aforesaid and serving, when said key is depressed to actuate the releasing-frame aforesaid; all the parts being constructed, arranged and operating in such a manner that they allow of the effective depressing of a succeeding key while the key aforesaid is still held down.

108. In combination, in a keyboard printing instrumentality, (a) a key; (b) a type-controlling member; (c) a connection intermediate said key and said type-controlling member wherethrough said key, when depressed, gives movement to said type-controlling member; and (d) an electromagnet, for acting upon the connection aforesaid intermediate the key aforesaid and the type-controlling member aforesaid to permit the type-controlling member aforesaid to return toward its normal position in advance of the release of the key aforesaid; all the parts being constructed, arranged and operating in such a manner that they allow of the effective depressing of a succeeding key while the key aforesaid is still held down.

109. In combination, in a keyboard printing instrumentality, (a) a type-controlling element; (b) a key; (c) a normally-stationary motor device; (d) a motor-controlling device, actuated by the key aforesaid and serving when said key is depressed to bring the motor device aforesaid into action to operate the type-controlling element aforesaid; and (e) a releasing means for the motor-controlling device aforesaid whereby said motor-controlling device is left free to return toward its normal position in advance of the release of the key depressed; all the parts being constructed, arranged and operating in such a manner that they allow of the effective depressing of a succeeding key while the key aforesaid is still held down.

110. In combination, in a keyboard print-

ing instrumentality, (a) a key; (b) a type-controlling member; (c) a latch, intermediate said key and said type-controlling member; (d) a motor, acting to free said latch; and (e) a motor-controlling device, operated by the type-controlling member aforesaid, serving when the key aforesaid is depressed, to bring the motor aforesaid into action to free the latch aforesaid, thereby to permit the type-controlling member aforesaid to return toward its normal position in advance of the release of the key depressed; all the parts being constructed, arranged and operating in such a manner that they allow of the effective depressing of a succeeding key while the key aforesaid is still held down.

111. In combination, in a keyboard printing instrumentality, (a) a type-controlling element; (b) a motor device, for impelling said type-controlling element; (c) a motor-controlling device; (d) a key; (e) a releasable connection, intermediate said key and said motor-controlling device, wherethrough said key, when depressed, actuates said motor-controlling device; said motor-controlling device operating, when thus actuated, to bring the motor aforesaid into action to operate the type-controlling element aforesaid; said motor device also acting upon the releasable connection aforesaid to permit the return of the motor-controlling device aforesaid toward its normal position, whereby the power is cut off automatically from said motor device and the type-controlling element aforesaid left free to return toward its normal position in advance of the release of the key depressed, so that another key may be depressed before the key first mentioned is released.

112. In a keyboard printing instrumentality, a type-selecting mechanism, including, (a) a plurality of keys; (b) type-controlling members, corresponding to said keys; (c) releasable connections intermediate said keys and type-controlling members, a releasable connection intermediate each key and the corresponding type-controlling member, wherethrough movement is communicated from said key to said type-controlling member when said key is depressed; and (d) a common releaser, normally stationary, but controlled by the keys aforesaid and acting, when a key is depressed, upon the releasable connection intermediate said key and the corresponding type-controlling member, to permit said type-controlling member to return toward its normal position in advance of the release of the key depressed, whereby another key may be depressed while the key first depressed is still held down.

113. In a keyboard printing instrumentality, a type-selecting mechanism, including, (a) a plurality of keys; (b) type-controlling members, corresponding to said keys; (c) latches intermediate said keys and type-controlling members, a latch intermediate each key and the corresponding type-controlling member, wherethrough movement is commu-

nicated when a key is depressed from said key to the corresponding type-controlling member; and (d) a vibratory releasing-frame, common to the latches aforesaid; said releasing-frame being normally stationary, but acting, when a key is depressed, to free the latch intermediate said key and the corresponding type-controlling member, to permit said type-controlling member to return toward its normal position in advance of the release of the key depressed, whereby another key may be depressed while the key first depressed is still held down.

114. In a keyboard printing instrumentality, a type-selecting mechanism, including, (a) a plurality of keys; (b) type-controlling members, corresponding to said keys; (c) pivoted latches intermediate said keys and type-controlling members, a pivoted latch intermediate each key and the corresponding type-controlling member, wherethrough movement is communicated when said key is depressed from said key to the corresponding type-controlling member; (d) a returning-spring for said latch; and (e) a vibratory releasing-frame, common to a plurality of said latches for freeing the same, each as required; each of said latches being formed in such manner that when in its normal position it is clear of the releasing-frame and not affected by the releasing movement of said frame, but comes, when moved by the depressing of the corresponding key, into the path of said releasing-frame, so that it is struck and freed thereby, whereby the type-controlling member corresponding to a key depressed is left free to return toward its normal position in advance of the release of said key, so that another key may be depressed while the key first depressed is still held down.

115. In a keyboard printing instrumentality, a type-selecting mechanism, including, (a) a plurality of keys; (b) type-controlling members, corresponding to the keys aforesaid, and each actuated by the key with which it corresponds; and (c) a normally-stationary intermittently-vibratory motor device, controlled by the keys aforesaid and acting, when a key is depressed, to trip the type-controlling member corresponding to said key, all the parts being constructed, arranged and operating in such a manner that they allow of the effective depressing of a succeeding key while the key first depressed is still held down.

116. In a keyboard printing instrumentality, a type-selecting mechanism, including, (a) a plurality of keys; (b) type-controlling members, corresponding respectively to the keys aforesaid; (c) releasable connections intermediate said keys and type-controlling members, a releasable connection intermediate each key and the corresponding type-controlling member wherethrough, when a key is depressed, movement is communicated to the corresponding type-controlling member; (d) a releasing-frame for acting on said re-

leasable connections, each as required, to permit the type-controlling member corresponding to the key depressed to return toward its normal position in advance of the release of said key; (e) another frame, operated by the type-controlling members aforesaid; and (f) means, controlled by the frame last mentioned, for actuating the releasing-frame aforesaid.

117. In a keyboard printing instrumentality, a type-selecting mechanism, including, (a) a plurality of keys; (b) type-controlling members, corresponding respectively to the keys aforesaid; (c) releasable connections intermediate said keys and type-controlling members, a releasable connection intermediate each key and the corresponding type-controlling member wherethrough, when a key is depressed, movement is communicated to the corresponding type-controlling member; (d) a releasing-frame for acting on said releasable connections, each as required, to permit the type-controlling member corresponding to the key depressed to return toward its normal position in advance of the release of said key; (e) another key-operated frame, and (f) a normally-stationary intermittently-vibratory motor device, controlled by the frame last mentioned, and serving to actuate the releasing-frame aforesaid.

118. In a keyboard printing instrumentality, a type-selecting mechanism, including, (a) a plurality of keys; (b) type-controlling members, corresponding to the keys aforesaid, and each actuated by the key with which it corresponds; and (c) electrically-operated tripping mechanism, acting, when a key is depressed, to trip the type-controlling member corresponding to said key, thereby to permit the depressing of another key while the key first depressed is still held down.

119. In a keyboard printing instrumentality, a type-selecting mechanism, including, (a) a plurality of keys; (b) type-controlling members, corresponding to the keys aforesaid; (c) latches intermediate said keys and said type-controlling members each latch serving to communicate movement from the corresponding key when it is depressed, to the corresponding type-controlling member; (d) a tripper, common to a plurality of said latches; and (e) an electromagnet for actuating said tripper.

120. In a keyboard printing instrumentality, a type-selecting mechanism, including, (a) a plurality of keys; (b) type-controlling members, corresponding to the keys aforesaid; (c) latches intermediate said keys and said type-controlling members, each latch serving to communicate movement from the corresponding key when it is depressed, to the corresponding type-controlling member; (d) a tripper, common to a plurality of said latches; (e) an electromagnet for actuating said tripper; and (f) a frame, controlling the circuit of said electromagnet; said frame being operated by keys aforesaid through the

type-controlling members aforesaid, whereby when a key is depressed the type-controlling member corresponding thereto is left free to return toward its normal position, so that another key may be depressed while the key first depressed is still held down.

121. In a keyboard printing instrumentality, a type-selecting mechanism, including, (a) a plurality of type-controlling elements; (b) a single normally-stationary but intermittently-vibratory motor device for actuating said type-controlling elements, each as required; said type-controlling elements being normally disconnected from said motor device; (c) keys; (d) means operated by said keys for connecting the type-controlling elements aforesaid, each as required, with the motor device aforesaid, and for bringing said motor device into action to impel the type-controlling elements thus connected with it; and (e) releasing means, whereby a type-controlling element, connected with the motor device aforesaid upon the depressing of a key, is disconnected from said motor device in advance of the release of the key depressed, all the parts being constructed, arranged and operating in such a manner that when a key is depressed to select or make a letter, another key can be depressed to select or make a succeeding letter, while the key first depressed is still held down.

122. In a keyboard printing instrumentality, a type-selecting mechanism, including, (a) a plurality of type-controlling elements; (b) a motor device for impelling said type-controlling elements, each as required; said type-controlling elements being normally disconnected from said motor device; (c) keys; (d) means operated by said keys for connecting the type-controlling elements aforesaid with the motor device aforesaid, each type-controlling element as required; (e) a motor-controlling device operated by the keys aforesaid and serving, when a key is depressed, to bring the motor device aforesaid into action for the impelling of the type-controlling element corresponding to the key depressed; and (f) releasing means, whereby said motor-controlling device is left free, when a key is depressed, to return toward its normal position in advance of the release of said key, and whereby the type-controlling element aforesaid is disconnected from the motor device aforesaid in advance of the release of said key, all the parts being constructed, arranged and operating in such a manner that when a key is depressed to select or make a letter, another key can be depressed to select or make a succeeding letter, while the key first depressed is still held down.

123. In a keyboard printing instrumentality, a type-selecting mechanism, including, (a) a plurality of type-controlling elements; (b) a single motor device for actuating a plurality of said type-controlling elements, each as required; (c) keys; (d) levers, corresponding respectively to and actuated respectively

by said keys; (e) latches, intermediate said keys and said levers, a latch for each key and the corresponding lever; (f) means, operated by said levers, for connecting the type-controlling elements aforesaid, each as required, with the motor device aforesaid, and for bringing said motor device into action to operate the type-controlling element connected with it when a key is depressed; and (g) a releasing-frame, for freeing the latches aforesaid, to permit the levers aforesaid actuated by the keys aforesaid to return to their normal positions in advance of the release of the key depressed, whereby another key may be depressed without releasing the key first depressed.

124. In a keyboard printing instrumentality, a type-selecting mechanism, including, (a) a plurality of type-controlling elements; (b) a vibratory frame, normally stationary, for giving movement to the type-controlling elements aforesaid, each as required, said type-controlling elements being normally disconnected from said frame; (c) keys; (d) means operated by said keys for connecting the type-controlling elements aforesaid, each as required, with the vibratory frame aforesaid; (e) means, operated by said keys, acting, when a key is depressed, to give movement to the vibratory frame aforesaid, to actuate the type-controlling element connected with it; (f) means, whereby the vibratory frame aforesaid and the type-controlling element actuated thereby are permitted to return toward their normal positions in advance of the release of the key depressed, and whereby the type-controlling element aforesaid is disconnected from the vibratory frame aforesaid in advance of the release of the key depressed, all the parts being constructed, arranged and operating in such a manner that when a key is depressed to select or make a letter, another key can be depressed to select or make a succeeding letter, while the key first depressed is still held down.

125. In a keyboard printing instrumentality, a type-selecting mechanism, including, (a) a plurality of type-controlling elements; (b) a vibratory frame, normally stationary, for giving movement to the type-controlling elements aforesaid, each as required, said type-controlling elements being normally disconnected from said frame; (c) keys; (d) levers, corresponding to and actuated by said keys; (e) latches intermediate said keys and said levers, a latch for each key and the corresponding lever; (f) means, operated by said levers for connecting the type-controlling elements aforesaid, each as required, with the vibratory frame aforesaid; (g) a releasing-frame, for acting on the latches aforesaid to release the levers aforesaid, actuated by the keys aforesaid through said latches; (h) motor mechanism for actuating the vibratory frame aforesaid and the releasing-frame aforesaid; (i) motor-controlling means operated by the keys aforesaid, and serving, when

a key is depressed, to bring the motor mechanism aforesaid into action, to operate the vibratory frame aforesaid, and the type-controlling element connected therewith by the 5 key depressed, and also to operate the releasing-frame aforesaid to free the latch operated by the key depressed, permitting the lever aforesaid operated by said key through said latch and the motor-controlling means 10 operated by said key through said latch and lever, to return toward their normal positions, cutting off power from the motor device aforesaid, so that the vibratory frame aforesaid and the releasing-frame aforesaid 15 return toward their normal positions in advance of the release of the key depressed, whereby another key may be depressed while the key first depressed is still held down.

126. In a keyboard printing instrumentality, a type-selecting mechanism, including, 20 (a) a plurality of type-controlling elements; (b) a vibratory frame for giving movement to said type-controlling elements, each as required; said frame being normally at rest, and said type-controlling elements being normally disconnected therefrom; (c) an electromagnet for actuating said frame; (d) keys; (e) means, controlled by said keys, whereby, when a key is depressed, the proper 25 type-controlling element is brought into operative relation with the vibratory frame aforesaid to receive movement therefrom; (f) a circuit-controller common to a plurality of the keys aforesaid, and controlling the circuit of the electromagnet aforesaid, each of 30 said keys acting, when depressed, to give movement to said circuit-controlling frame, to bring the magnet aforesaid into action to impel the vibratory frame aforesaid; and (g) 35 a releasing means, whereby said circuit-controlling frame, when actuated by the depressing of a key, is left free to return toward its normal position in advance of the release of said key, to permit a succeeding key or keys 40 to be depressed without having first to release the key previously depressed.

127. In a keyboard printing instrumentality, a type-selecting mechanism, including, 45 (a) a plurality of type-controlling elements; (b) a vibratory frame for giving movement to said type-controlling elements, each as required; said frame being normally at rest, and said type-controlling elements being normally disconnected therefrom; (c) keys; (d) 50 levers corresponding to and actuated by said keys; (e) latches intermediate said keys and said levers, a latch for each key and the corresponding lever, wherethrough movement is communicated from said key, when depressed, to the corresponding lever; (f) means, operated by the levers aforesaid, for connecting the type-controlling elements, aforesaid, each as required, with the vibratory frame aforesaid, to receive movement therefrom; (g) a 55 releasing-frame for acting on said latches to permit the levers aforesaid operated by the keys aforesaid to return toward their normal 60

positions in advance of the release of the keys depressed, corresponding to them; (h) electromagnetic means for actuating the vibratory frame aforesaid and the releasing-frame aforesaid; and (i) circuit-controlling means, 65 actuated by the keys aforesaid, controlling the electromagnetic means above mentioned; whereby, when a key is depressed, the vibratory frame aforesaid is caused to act to impel the type-controlling element connected with it by the key depressed, and the releasing-frame aforesaid caused to operate upon the latch corresponding to the key depressed, 70 to permit the return of the lever corresponding to said key, and the parts operated thereby toward their normal positions in advance of the release of the key depressed, so that another key may be depressed without releasing the key first depressed.

128. In a keyboard printing instrumentality, a type-selecting mechanism, including, 75 (a) a plurality of type-controlling elements; (b) a vibratory frame for giving movement to 80 said type-controlling elements, each as required; said frame being normally at rest, and said type-controlling elements being normally disconnected therefrom; (c) keys; (d) levers corresponding to and actuated by said 85 keys; (e) latches intermediate said keys and said levers, a latch for each key and the corresponding lever, wherethrough movement is communicated from said key, when depressed, to the corresponding lever; (f) means, operated by the levers aforesaid, for connecting the type-controlling elements aforesaid, each as required, with the vibratory frame aforesaid, to receive movement therefrom; (g) a 90 releasing-frame for acting on said latches to 95 permit the levers aforesaid, operated by the keys aforesaid, to return toward their normal 100 positions in advance of the release of the keys depressed, corresponding to them; (h) an electromagnet, actuating both the vibratory 105 frame aforesaid and the releasing-frame aforesaid; and (i) circuit-controlling means, operated by the keys aforesaid through the latches aforesaid, and controlling the electromagnet aforesaid.

129. In a keyboard printing instrumentality and in combination (a) a plurality of keys; (b) levers, corresponding to said keys; (c) type-selecting means, operated by said levers; (d) latches intermediate said keys and said 110 levers, a latch for each key and the corresponding lever; and (e) a releasing-frame common to a plurality of said latches for acting when a key is depressed, upon the latch intermediate said key and the corresponding 115 one of the levers aforesaid to permit the return of said lever toward its normal position, in advance of the release of the key depressed.

130. In a keyboard printing instrumentality and in combination, (a) a plurality of keys; (b) levers, corresponding to said keys; (c) type-selecting means, operated by said levers; (d) releasable connections intermediate said 130 keys and said levers; and (e) a motor device,

normally stationary, but controlled by the keys aforesaid and acting, when a key is depressed, upon the releasable connection intermediate said key and the corresponding 5 one of the levers aforesaid, to trip said lever, all the parts being constructed, arranged and operating in such a manner that when a key is depressed to select or make a letter, another key can be depressed to select or make 10 a succeeding letter, while the key first depressed is still held down.

131. In a keyboard printing instrumentality, and in combination, (a) a plurality of keys; (b) levers, corresponding to and actuated by 15 said keys; (c) type-selecting means, operated by said levers; (d) a motor device, normally inactive, but serving, when called into action, to trip the levers aforesaid; (e) a motor-controlling device, operated by the levers aforesaid and serving to bring the motor device aforesaid into action when a key is depressed and acting, when the trip takes place, to cut off power from said motor device to permit the return of the parts toward their normal 25 positions in advance of the release of the key depressed; all the parts being constructed, arranged and operating in such a manner that when a key is depressed to select or make a letter, another key can be depressed to select or 30 make a succeeding letter, while the key first depressed is still held down.

132. In a keyboard printing instrumentality, and in combination, (a) keys; (b) levers, corresponding to said keys; (c) type-selecting 35 means, operated by said levers; (d) pivoted latches intermediate said keys and said levers, a latch for each key and the corresponding lever; (e) a releasing-frame common to a plurality of said latches, for freeing said 40 latches, each as required; (f) a motor device for actuating said releasing-frame; and (g) a motor-controlling device, operated by the levers aforesaid, and controlling the motor device aforesaid.

45 133. In a keyboard printing instrumentality and in combination, (a) keys; (b) levers, corresponding to said keys; (c) type-selecting means, operated by said levers; (d) releasable connections intermediate said keys and 50 said levers wherethrough said keys give movement to said levers; and (e) electrically-operated means acting, when a key is depressed, upon the releasable connection intermediate said key and the corresponding one of the levers aforesaid to trip said lever, whereby another key may be depressed while the key first depressed is still held down.

134. In a keyboard printing instrumentality, and in combination, (a) keys; (b) levers, 60 corresponding to said keys; (c) type-selecting means, operated by said levers; (d) pivoted latches intermediate said keys and said levers, a latch for each key and the corresponding lever; (e) a releasing-frame common to a plurality of the latches aforesaid, for freeing said latches each as required; (f) an electromagnet for actuating said releasing-frame;

and (g) means operated by the levers aforesaid for controlling said magnet.

135. In combination in a keyboard printing 70 instrumentality, (a) an alphabet of type-controlling devices; (b) members, fewer in number than said type-controlling devices, and means controlled by different combinations of said members for operating the type-controlling devices aforesaid, each as required; (c) keys, corresponding to and controlling 75 said members; and (d) releasing means for the members aforesaid, operating, when a key is depressed, to permit that one of the members aforesaid corresponding to and controlled by the key depressed, to return toward its normal position in advance of the release of said key, whereby another key may be depressed while the key first depressed is still held down.

136. In combination in a keyboard printing instrumentality, (a) an alphabet of type-controlling devices; (b) members fewer in number than said type-controlling devices, and 90 means controlled by said members for operating said type-controlling devices, each as required; (c) keys, corresponding to and controlling said members; (d) latches, intermediate said keys and said members, a latch for 95 each key and the corresponding member; and (e) a releasing device, common to a plurality of said latches, and serving, when a key is depressed, to act upon the latch corresponding to said key to permit the member aforesaid corresponding to said key, to return toward its normal position in advance of the release of said key, whereby another key may be depressed while the preceding key is still held down.

137. In combination in a keyboard printing instrumentality, (a) an alphabet of type-controlling devices; (b) members fewer in number than said type-controlling devices, and means controlled by different combinations 100 of said members for operating the type-controlling devices aforesaid, each as required; (c) keys, corresponding to and controlling said members; (d) connections intermediate 105 said keys and said members; (e) a motor; and (f) a controlling device for said motor, said controlling device being operated by the keys aforesaid through the members aforesaid; said motor acting, when a key is depressed, upon the connection intermediate said key 110 and the member aforesaid controlled thereby, to permit said member to return toward its normal position in advance of the release of said key, whereby another key may be depressed while the key first depressed is still held down.

138. In combination in a keyboard printing instrumentality, (a) an alphabet of type-controlling devices; (b) members fewer in number than said type-controlling devices, and 130 means controlled by said members for operating said type-controlling devices, each as required; (c) keys, corresponding to and controlling said members; (d) latches, interme-

diate said keys and said members, a latch for each key and the corresponding member; (e) a releasing-frame, common to a plurality of said latches; and (f) an electromagnet for actuating said releasing-frame; said releasing-frame acting, when a key is depressed, upon the latch corresponding to said key, to permit the member operated by said key through said latch to return toward its normal position in advance of the release of said key, whereby another key may be depressed while the key first depressed is still held down.

139. In combination in a keyboard printing instrumentality, (a) an alphabet of type-controlling devices; (b) members, fewer in number than said type-controlling devices, and means controlled by said members for operating said type-controlling devices, each as required; (c) keys, corresponding to and controlling said members; (d) releasable connections intermediate said keys and said members; (e) an electromagnet for freeing a plurality of said releasable connections; (f) a circuit-controller for said magnet, operated by keys aforesaid, whereby, when a key is depressed, the magnet aforesaid is brought into action to free the releasable connection between said key and the member aforesaid corresponding to and controlled by said key, to permit said member to return toward its normal position in advance of the release of said key, whereby another key may be depressed while the key first depressed is still held down.

140. In combination in a type-writing machine, (a) means for printing; (b) keys controlling said printing means; (c) paper-feeding mechanism including a paper-carriage and letter-spacing mechanism therefor, for advancing the paper step by step as the letters are printed; (d) a device whereby the movement of the carriage may be enlarged to provide for an interverbal space; (e) a key at the keyboard controlling said space-enlarging device, said key acting, when depressed, to cause a movement of said space-enlarging device wherefrom an increased movement of the paper-carriage ensues; and (f) releasing means whereby said space-enlarging device, when the key aforesaid controlling it is depressed, is left free to return toward its normal position in advance of the release of said key.

141. In combination in a type-writing machine, (a) means for printing; (b) keys controlling said printing means; (c) paper-feeding mechanism including a paper-carriage and letter-spacing mechanism therefor, for advancing the paper step by step as the letters are printed; (d) a device whereby the movement of the carriage may be enlarged to provide for an interverbal space; (e) a key at the keyboard for controlling said space-enlarging device; (f) a latch intermediate said key and said space-enlarging device wherethrough said key, when depressed, gives movement to said space-enlarging device to cause a movement of said space-enlarging de-

vice, wherefrom an increased movement of the paper-carriage ensues; and (g) means, acting when said key is depressed to free said latch, thereby to permit said space-enlarging device to return toward its normal position in advance of the release of the key.

142. In combination in a type-writing machine, (a) means for printing; (b) keys controlling said printing means; (c) paper-feeding mechanism including a paper-carriage and letter-spacing mechanism therefor, for advancing the paper step by step as the letters are printed; (d) a device whereby the movement of the carriage may be enlarged to provide for an interverbal space; (e) a key at the keyboard for controlling said space-enlarging device; (f) a latch intermediate said key and said space-enlarging device wherethrough said key, when depressed, gives movement to said space-enlarging device to cause a movement of said space-enlarging device wherefrom an increased movement of the paper-carriage ensues; and (g) a motor, acting when said key is depressed, to free said latch, thereby to permit said space-enlarging device to return toward its normal position in advance of the release of the key.

143. In combination in a type-writing machine, a paper-carriage and letter-spacing mechanism therefor, including, (a) a fast dog; (b) a loose dog; (c) a toothed part connected with the carriage and with which said dogs alternately engage; (d) means for actuating said dogs; (e) a stop for the loose dog aforesaid; said stop being mounted to move out of position to cause or permit an increased movement of said loose dog; (f) a key, controlling said loose-dog stop; and (g) releasing means whereby, when said key is depressed, and said stop thereby moved from its normal position so as to permit an increased movement of the loose dog aforesaid, said loose-dog stop is permitted to return toward its normal position in advance of the release of said key.

144. In combination in a type-writing machine, a paper-carriage and letter-spacing mechanism therefor, including (a) a fast dog; (b) a loose dog; (c) a toothed part connected with the carriage and with which said dogs alternately engage; (d) means for actuating said dogs; (e) a stop for the loose dog aforesaid; said stop being mounted to move out of position to cause or permit an increased movement of said loose dog; (f) a key for controlling said loose-dog stop; (g) a latch intermediate said key and said loose-dog stop, wherethrough said key when depressed, gives movement to said loose-dog stop to move it from its normal position, so that it permits an increased movement of the paper-carriage; and (h) means, acting when said key is depressed to free said latch, thereby to permit the loose-dog stop aforesaid to return toward its normal position in advance of the release of the key.

145. In combination in a type-writing ma-

chine, a paper-carriage and letter-spacing mechanism therefor, including (a) a fast dog; (b) a loose dog; (c) a toothed part connected with the carriage and with which said dogs alternately engage; (d) means for actuating said dogs; (e) a stop for the loose dog aforesaid; said stop being mounted to move out of position to cause or permit an increased movement of said loose dog; (f) a key for controlling said loose-dog stop; (g) a latch intermediate said key and said loose-dog stop, wherethrough said key when depressed, gives movement to said loose-dog stop to move it from its normal position, so that it permits an increased movement of the paper-carriage; and (h) a motor device, acting when said key is depressed, to free said latch, thereby to permit the loose-dog stop aforesaid to return toward its normal position in advance of the release of the key.

146. In combination in a type-writing machine, (a) a plurality of type-bars striking to a common printing-center; (b) keys and means controlled thereby for actuating said type-bars; said means including latches intermediate said keys and the devices operated by them; (c) a paper-carriage; (d) letter-spacing mechanism, whereby said paper-carriage is fed step by step, as the letters are printed; (e) a device whereby the movement of said carriage may be enlarged to provide for an interverbal space; (f) a space-key at the keyboard for controlling said space-enlarging device; (g) a latch intermediate said key and said space-enlarging device wherethrough said key when depressed, gives movement to said space-enlarging device to cause a movement of said device, wherfrom an increased movement of the paper-carriage ensues; and (h) a releasing device common to the latch last mentioned and to a plurality of the latches above mentioned, for freeing said latches, each as required.

147. In combination in a type-writing machine, (a) a plurality of type-bars striking to a common printing-center; (b) keys and means controlled thereby for actuating said type-bars; said means including latches intermediate said keys and the devices operated by them; (c) a paper-carriage; (d) letter-spacing mechanism, whereby said paper-carriage is fed step by step, as the letters are printed; (e) a device whereby the movement of said carriage may be enlarged to provide for an interverbal space; (f) a space-key at the keyboard for controlling said space-enlarging device; (g) a latch intermediate said key and said space-enlarging device wherethrough said key when depressed, gives movement to said space-enlarging device to cause a movement of said device, wherfrom an increased movement of the paper-carriage ensues; (h) a vibratory frame, common to the latch last mentioned and to a plurality of the other latches above mentioned, for freeing said latches, each as required; and (i) a mo-

tor device for giving movement to said vibratory frame.

148. In combination in a type-writing machine, (A) a plurality of type-bars striking to a common printing-center; (B) keys and means controlled thereby for actuating said type-bars; said means including latches intermediate said keys and the devices operated by them; (C) a paper-carriage and letter-spacing mechanism therefor, including (a) a fast dog; (b) a loose dog; (c) a toothed part connected with the carriage with which said dogs alternately engage as they are actuated; (d) a stop for the loose dog aforesaid, said stop being mounted to move out of position to permit an increased movement of said loose dog; (e) a key at the keyboard for controlling said loose-dog stop; and (f) a latch intermediate said key and said loose-dog stop, wherethrough said key when depressed, gives movement to said loose-dog stop to move said loose-dog stop from its normal position, so that it permits an increased movement of the loose dog aforesaid, and of the paper-carriage; and (D) a releasing device common to the latch last mentioned and to a plurality of the other latches above mentioned, for freeing said latches, each as required.

149. In combination in a type-writing machine, (A) a plurality of type-bars striking to a common printing-center; (B) keys and means controlled thereby for actuating said type-bars; said means including latches intermediate said keys and the devices operated by them; (C) a paper-carriage and letter-spacing mechanism therefor, including (a) a fast dog; (b) a loose dog; (c) a toothed part connected with the carriage, with which said dogs alternately engage as they are actuated; (d) a stop for the loose dog aforesaid, said stop being mounted to move out of position to permit an increased movement of said loose dog; (e) a key at the keyboard for controlling said loose-dog stop; and (f) a latch intermediate said key and said loose-dog stop, wherethrough said key when depressed, gives movement to said loose-dog stop to move said loose-dog stop from its normal position, so that it permits an increased movement of the loose dog aforesaid, and of the paper-carriage; (D) a vibratory frame, common to the latch last mentioned and to a plurality of the other latches above mentioned, for freeing said latches, each as required; and (E) a motor device for giving movement to said vibratory frame.

150. In combination in a type-writing machine, (a) a plurality of type-bars striking to a common printing-center; (b) motor mechanism for impelling said type-bars; (c) keys for controlling said type-bars; (d) latches intermediate said keys and the devices controlled by them; (e) a paper-carriage; (f) letter-spacing mechanism, whereby said paper-carriage is fed step by step as the letters are printed; (g) a device whereby the movement

of said paper-carriage may be enlarged to provide for an interverbal space; (h) a space-key at the keyboard, for controlling said space-enlarging device; (i) a latch intermediate said key and said space-enlarging device, wherethrough said key, when depressed, gives movement to said space-enlarging device to cause a movement of said device, wherefrom an increased movement to the paper-carriage ensues; and (k) releasing mechanism for the latches aforesaid; acting when the space-key aforesaid and one of the other keys aforesaid are depressed simultaneously, to free the latches corresponding to the keys depressed in advance of the release of said keys.

151. In combination in a type-writing machine, (a) a plurality of type-bars striking to a common printing-center; (b) motor mechanism for impelling said type-bars; (c) keys for controlling said type-bars; (d) latches intermediate said keys and the devices controlled by them; (e) a paper-carriage; (f) letter-spacing mechanism whereby said paper-carriage is fed step by step as the letters are printed; (g) a device whereby the movement of said paper-carriage may be enlarged to provide for an interverbal space; (h) a space-key at the keyboard for controlling said space-enlarging device; (i) a latch intermediate said key and said space-enlarging device, wherethrough said key when depressed, gives movement to said space-enlarging device to cause a movement of said device, wherefrom an increased movement to the paper-carriage ensues; (k) a vibratory frame, common to the latch last mentioned, and to a plurality of the other latches above mentioned, for freeing said latches, each as required, and (l) a motor, for actuating said frame.

152. In combination in a type-writing machine, (a) a plurality of type-bars striking to a common printing-center; (b) a motor device common to a plurality of said type-bars for actuating said type-bars, each as required; said motor being normally inactive and said type-bars being normally disconnected therefrom; (c) keys for controlling said type-bars; (d) devices actuated by said keys, for connecting said type-bars, each type-bar as required, with the motor device aforesaid; (e) latches intermediate the keys aforesaid and the key-actuated devices last above mentioned; (f) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (g) a paper-carriage; (h) letter-spacing mechanism whereby said paper-carriage is fed step by step as the letters are printed; (i) a device whereby the movement of said paper-carriage may be enlarged to provide for an interverbal space; (k) a space-key at the keyboard, for controlling said space-enlarging device; (l) a latch intermediate said key and said space-enlarging device, wherethrough said key, when depressed, controls said space-enlarging device to cause a movement of said device, wherefrom an increased movement to the paper-carriage ensues; and (m) a releasing-frame common to the latch last mentioned and to a plurality of the other latches above mentioned, for freeing said latches each as required.

153. In combination in a type-writing machine, (a) a plurality of type-bars striking to a common printing-center; (b) a motor device common to a plurality of said type-bars for actuating said type-bars, each as required; said motor being normally inactive and said type-bars being normally disconnected therefrom; (c) keys for controlling said type-bars; (d) devices actuated by said keys, for connecting said type-bars, each type-bar as required, with the motor device aforesaid; (e) latches intermediate the keys aforesaid and the key-actuated devices last above mentioned; (f) means for bringing the motor aforesaid into action, said motor-controlling means being operated by the keys aforesaid through the latches aforesaid, each key when depressed, acting through its latch upon the other devices controlled by said key, to connect one of the type-bars aforesaid with the motor aforesaid, and to bring said motor into action to operate said type-bar; (g) a paper-carriage; (h) letter-spacing mechanism for the latches aforesaid, acting when the space-key aforesaid and one of the other keys aforesaid are depressed simultaneously, to free the latches corresponding to the keys depressed in advance of the release of said keys.

154. In combination in a type-writing machine, (a) a plurality of type-bars striking to a common printing-center; (b) a motor device common to a plurality of said type-bars for actuating said type-bars, each as required; said motor being normally inactive and said type-bars being normally disconnected therefrom; (c) keys for controlling said type-bars; (d) devices actuated by said keys, for connecting said type-bars, each type-bar as required, with the motor device aforesaid; (e) latches intermediate the keys aforesaid and the key-actuated devices last above mentioned; (f) means for bringing the motor aforesaid into action, said motor-controlling means being operated by the keys aforesaid through the latches aforesaid, each key when depressed, acting through its latch upon the other devices controlled by said key, to connect one of the type-bars aforesaid with the motor aforesaid, and to bring said motor into action to operate said type-bar; (g) a paper-carriage; (h) letter-spacing mechanism, whereby said paper-carriage is fed step by step as the letters are printed; (i) a device whereby the movement of said paper-carriage may be enlarged to provide for an interverbal space; (k) a space-key at the keyboard, for controlling said space-enlarging device; (l) a latch intermediate said key and said space-enlarging device, wherethrough said key, when depressed, controls said space-enlarging device to cause a movement of said device, wherefrom an increased movement to the paper-carriage ensues; and (m) a releasing-frame common to the latch last mentioned and to a plurality of the other latches above mentioned, for freeing said latches each as required.

155. In combination in a type-writing machine, (a) a plurality of type-bars striking to a common printing-center; (b) a motor device common to a plurality of said type-bars for actuating said type-bars, each as required; said motor being normally inactive and said type-bars being normally disconnected therefrom; (c) keys for controlling said type-bars; (d) devices actuated by said keys, for connecting said type-bars, each type-bar as required, with the motor device aforesaid; (e) latches intermediate the keys aforesaid and the key-actuated devices last above mentioned; (f) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (g) a paper-carriage; (h) letter-spacing mechanism whereby said paper-carriage is fed step by step as the letters are printed; (i) a device whereby the movement of said paper-carriage may be enlarged

aforesaid into action, said motor-controlling means being operated by the keys aforesaid through the latches aforesaid, each key when depressed acting through its latch upon the other devices controlled by said key, to connect one of the type-bars aforesaid with the motor aforesaid, and to bring said motor into action to operate said type-bar; (g) a paper-carriage; (h) letter-spacing mechanism whereby said paper-carriage is fed step by step as the letters are printed; (i) a device whereby the movement of said paper-carriage may be enlarged to provide for an interverbal space; (k) a space-key at the keyboard for controlling said space-enlarging device; (l) a latch intermediate said key and said space-enlarging device wherethrough said key, when depressed controls said space-enlarging device to cause a movement of said device, wherefrom an increased movement to the paper-carriage ensues; and (m) a releasing-frame common to the latch last mentioned and to a plurality of the other latches above mentioned, for freeing said latches each as required; said frame being actuated by the type-bar-impelling motor aforesaid.

155. In combination in a type-writing machine, (A) a plurality of type-bars striking to a common printing-center; (B) a motor device common to a plurality of said type-bars for actuating said type-bars, each as required; said motor being normally inactive and said type-bars being normally disconnected therefrom; (C) keys for controlling said type-bars; (D) devices actuated by said keys, for connecting said type-bars, each type-bar as required, with the motor device aforesaid; (E) latches intermediate the keys aforesaid and the key-actuated devices last-mentioned; (F) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (G) a paper-carriage and letter-spacing mechanism therefor, including (a) a fast dog; (b) a loose dog; (c) a toothed part connected with the carriage with which said dogs alternately engage as they are actuated; (d) a stop for the loose dog aforesaid, said stop being mounted to move out of position to permit an increased movement of said loose dog; (e) a key at the keyboard for controlling said loose-dog stop; and (f) a latch intermediate said key and said loose-dog stop wherethrough said key when depressed controls said loose-dog stop to move said loose-dog stop from its normal position, so that it permits an increased movement of the loose dog aforesaid, and of the paper-carriage; and (H) a vibratory releasing-frame common to the latch last mentioned and to a plurality of the other latches above mentioned, for freeing said latches each as required.

156. In combination in a type-writing machine, (A) a plurality of type-bars striking to a common printing-center; (B) a motor device common to a plurality of said type-bars, for actuating said type-bars, each as required; said motor being normally inactive and said type-bars being normally disconnected therefrom; (C) keys for controlling said type-bars; (D) devices actuated by said keys, for connecting said type-bars, each type-bar as required, with the motor device aforesaid; (E) latches intermediate the keys aforesaid and the key-actuated devices last-mentioned; (F) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (G) a paper-carriage and letter-spacing mechanism therefor, including (a) a fast dog; (b) a loose dog;

latches corresponding to said keys depressed in advance of the release of said keys.

156. In combination in a type-writing machine, (A) a plurality of type-bars striking to a common printing-center; (B) a motor device common to a plurality of said type-bars for actuating said type-bars, each as required; said motor being normally inactive and said type-bars being normally disconnected therefrom; (C) keys for controlling said type-bars; (D) devices actuated by said keys, for connecting said type-bars, each type-bar as required, with the motor device aforesaid; (E) latches intermediate the keys aforesaid and the key-actuated devices last-mentioned; (F) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (G) a paper-carriage and letter-spacing mechanism therefor, including (a) a fast dog; (b) a loose dog; (c) a toothed part connected with the carriage with which said dogs alternately engage as they are actuated; (d) a stop for the loose dog aforesaid, said stop being mounted to move out of position to permit an increased movement of said loose dog; (e) a key at the keyboard for controlling said loose-dog stop; and (f) a latch intermediate said key and said loose-dog stop wherethrough said key when depressed controls said loose-dog stop to move said loose-dog stop from its normal position, so that it permits an increased movement of the loose dog aforesaid, and of the paper-carriage; and (H) a vibratory releasing-frame common to the latch last mentioned and to a plurality of the other latches above mentioned, for freeing said latches each as required.

157. In combination in a type-writing machine, (A) a plurality of type-bars striking to a common printing-center; (B) a motor device common to a plurality of said type-bars, for actuating said type-bars, each as required; said motor being normally inactive and said type-bars being normally disconnected therefrom; (C) keys for controlling said type-bars; (D) devices actuated by said keys, for connecting said type-bars, each type-bar as required, with the motor device aforesaid; (E) latches intermediate the keys aforesaid and the key-actuated devices last-mentioned; (F) means for bringing the motor aforesaid into action, said motor-controlling means being operated by the keys aforesaid through the latches aforesaid; each key when depressed, acting through its latch upon the other devices controlled by said key, to connect one of the type-bars aforesaid with the motor aforesaid, and to bring said motor into action to operate said type-bar; (G) a paper-carriage and letter-spacing mechanism therefor, including (a) a fast dog; (b) a loose dog;

(c) a toothed part connected with the carriage with which said dogs alternately engage as they are actuated; (d) a stop for the loose dog aforesaid, said stop being mounted to move 5 out of position to permit an increased movement of said loose dog; (e) a key at the keyboard for controlling said loose-dog stop; and (f) a latch intermediate said key and said loose-dog stop wherethrough said key when 10 depressed, controls said loose-dog stop to move said loose-dog stop from its normal position, so that it permits an increased movement of the loose dog aforesaid, and of the paper-carriage; and (H) a vibratory releas-

ing-frame common to the latch last mentioned 15 and to a plurality of the other latches above mentioned, for freeing said latches each as required; said frame being actuated by the type-bar-impelling motor aforesaid.

In testimony whereof I have hereunto set 20 my hand, at Washington, in the District of Columbia, this 30th day of June, A. D. 1998, in the presence of the subscribing witnesses whose names are hereto affixed.

THADDEUS CAHILL.
